CALCULATING MACHINE

David Y. Read, New York, N. Y., assignor to
Remington Rand Inc., Buffalo, N. Y., a cor-
poration of Delaware

Application November 25, 1938, Serial No. 242,345

17 Claims. (Cl. 235—60)

This invention relates to calculating machines, and particularly to that type of calculating machine which is provided with a printing mechanism, and which is designed for use in billing and inventory work as well as in straight calculating.

Previous to the present invention, the only printing calculating machines which were adapted for billing work were large machines. The present machine, while it has no typewriting mechanism, is particularly adapted to receive bills and orders, etc., of varying sizes, which bills may have been previously written as to items and individual prices, but upon which there have been made no extensions, or totals, or computations of any sort. The present machine will make all extensions, print any necessary sub-totals or totals, including transfer-totals from either accumulator, accumulate and print grand totals, print true negative totals; accomplish addition, subtraction, multiplication, and division; accomplish constant-factor work and will, generally perform all the functions of the larger machines except typewriting. The present machine is small, light, portable, and inexpensive to manufacture and is a printing calculator of the ten-key key-set type.

Stated generally the present invention consists of a main casting upon which are removably mounted several units of mechanism. In the embodiment described hereinafter there are eight removable units. One unit includes the digit keys, the back-space key, the multiplication key, the constant-factor key, and the digit key ball-lock; another unit includes the motor, the palm-bars, the motor-clutch and associated reduction gearing, the total-selecting key, the correction key, part of the multiplying mechanism, and the accumulator-shift key; a third unit includes the printing hammers and their associated springs; a fourth unit includes mechanism for tensioning and releasing the printing hammers, and also includes means for disabling printing during certain operations of the machine; a fifth unit includes the type sectors and their associated return-springs and, further, includes mechanism for controlling the action of the type sectors during totaling and sub-totaling operations of the machine; a sixth unit includes two accumulators, their shafts, associated springs, framing, and control bails; a seventh unit includes a plurality of sliding actuating-plates, their associated pendents, a bell-crank used in multiplying operations, and a lever for disabling the cam-carriage during totaling operations; the remaining unit includes part of the multiplying mechanism, the re-multiplying mechanism, the cam carriage, the carriage escapement mechanism, the carriage return mechanism, the cam-setting mechanism, the carriage back-spacing mechanism (with the exception of the back-space key itself) the constant-factor or repeat mechanism, and the cam-

rotating mechanism. The machine has been designed, so that generally these units, all of which are attached to the main casting, may be removed from the machine without removing any other unit.

At this point it is to be understood that terms such as "rightwardly," "leftwardly," etc., mean, respectively, unless otherwise particularly specified, toward the right-hand and toward the left-hand of an observer viewing the machine from the front.

Depression of a digit key of the present machine normally causes depression of one or another of a plurality of cams mounted in a carriage which carriage is moved, one step at a time, toward the left-hand side of the machine at every key-depression. The cams are depressed varying distances according to the values of the digit keys which are actuated to depress them. It is thus that amounts are entered into the cam-carriage. After any amount has been entered in the cam-carriage, the carriage rests in such a position that certain of its cams are exactly aligned with certain type sectors. The type sectors are so formed and the cam carriage is so positioned in the machine that, after an amount has been entered in the carriage, the depressed cams lie between upright portions of the type sectors. Thus, when a motor-control key is operated, the cams are rotated and they move the type sectors positively to position the type for printing. During ordinary cycles of addition, etc., movement of any type sectors releases mechanism which controls printing. Printing is accomplished at the end of the forward stroke of the type sectors. Each type sector carries a rack-segment and these segments engage, at proper times, the wheels of either or both of two accumulators, depending upon the operation being performed, so that addition, subtraction, multiplication, division, totaling, sub-totaling, transfer-totaling, repeated addition and subtraction, etc., may be accomplished. The rotation of the cams and the engagement and disengagement of the accumulators is accomplished by a series of sliding actuating plates, which are positively driven by a pitman bracket, which bracket is driven by a single-revolution clutch, through reduction gearing, from the motor. The correction key of the present machine, when operated, causes clearing and returning of the cam carriage to home position without affecting the accumulators. An accumulator shift key is used to preselect the particular accumulator in which amounts are to be added and subtracted, etc. The normal or home position of the cam carriage is such that the four leftmost cams are aligned with the four rightmost type sectors. This arrangement is decidedly advantageous in computations involving fractions, as it allows "pointing-off" or back-spacing of the

cam carriage. A point-off or back-space key is provided on the keyboard plate, and this key is manually operable to backspace the cam carriage one step at a time. Due to the fact that the home position of the cam carriage is not its extreme right-hand position, and due to the fact that during totaling operations the carriage is drawn completely away from and to the right of the type sectors, mechanism is provided for automatic carriage return from either direction to the home position, and mechanism is also provided for positively stopping and retaining the carriage in its home position after it has been returned.

The motor control of the machine is effected by the following keys:

1. In addition, by the "Add" palm-bar
2. In subtraction, by the "Subtract" palm-bar
3. In multiplication, by the digit keys
4. In re-multiplication, by the "Re-multiply" key and the digit keys
5. In division, by the digit keys
6. In sub-totaling, totaling, grand totaling, etc., by the "Total" palm-bar
7. In correcting, by the "Correction" key

Multiplication in the present machine (which is done by repeated addition) utilizes the digit keys as motor-control means, and the regular palm bars are not used at all in this function. For example, if it is desired to multiply 183 by 52, the amount 183 is first set up on the digit key-board. This operation depresses three cams and escapes the carriage, from home position, three steps to the left. A multiply key or lever is then actuated, and this conditions the multiplying actuating-plate for operation, but does not cycle the machine. Actuation of the multiply key also disables the cam-depressor and enables a motor control segment. The "2" digit key is now depressed, and this moves the motor-control segment two steps from its normal position. The motor-control segment then cycles the machine twice, and, at the end of the second cycle, the digit key returns to normal position and a carriage escapement occurs. The "5" digit key is then depressed and the motor-control segment is moved five steps from its normal position. The operator's finger is removed from the "5" key and the motor-control segment then acts, under spring pressure, to cycle the machine five times. On every cycle the "5" key is returned one-fifth of the distance from its depressed position to its normal position. It is to be understood that, during the above seven multiplication cycles, the multiply lever was manually held in its operative position and it is further to be understood that, during these cycles, no carriage return was effected. When the multiply lever is released, the cam carriage is automatically cleared and returned to home position, and the multiplying actuating-plate is returned to its normal position.

Division is accomplished by the use of a table of reciprocals, a well known process, the formula for which is—

$$a+b = a \times \frac{1}{b}$$

Thus, division is actually accomplished by a process of multiplication.

Subtraction is accomplished by the "direct" method. A subtrahend is set up on the digit key-board and the "Subtract" palm bar is depressed. This cycles the machine and, through operation of a subtract actuating-plate, throws the accumulator into mesh with the actuating racks at

the very beginning of the cycle. Hence, during subtraction cycles, the accumulator wheels are turned in a reverse direction from that in which they are turned during adding operations.

The re-multiply key on this machine does not, in and of itself, cause numbers to be multiplied and re-multiplied but, when depressed, causes any amount, which may have been entered into the upper accumulator, to be withdrawn from the accumulator and simultaneously inserted in the cams of the cam carriage. Then the amount, so transferred to the cam carriage, may on a subsequent cycle be multiplied by any other amount by using the multiply key and digit keys as has been previously explained. The re-multiply key is also used to print a true negative total as the present machine has no "fugitive one" mechanism. When the upper accumulator contains a negative amount or credit balance, this may be detected by the presence of a series of 9's, showing on the visible accumulator dials, to the left of the negative amount. For example, suppose that the machine operator sees 999176 standing upon the upper accumulator dials. This indicates that the machine contains a credit balance but does not show what this credit balance may be. The operator depresses the re-multiply key and the ensuing cycle clears the accumulator and impresses the amount 999176 upon the cams of the cam carriage. The "Subtract" palm-bar is then depressed and, at the end of this cycle, the dials of the accumulator read 000824. A total is then taken and, during this cycle, the true negative amount which was represented on the dials when they stood at 999176 is printed. A grand-re-multiply key is located near the re-multiply key, and if the grand-re-multiply key is held depressed while the regular re-multiply key is being depressed, then the ensuing cycle will not affect the upper accumulator, but will clear the lower or grand accumulator and impress the amount taken from the grand accumulator upon the cams of the cam carriage.

The constant-factor key of the present invention is adapted to be latched down for a number of cycles, if desired, and must be manually released after being thus latched. The key acts much the same as the usual adding machine "repeat-key," in that it disables the carriage return mechanism of the machine. Also, if the constant-factor key is latched down, and a total is taken, then, at the end of such a total cycle, the cam carriage will not be cleared and will move toward the left-hand side of the machine and stop at a predetermined position according to the "constant factor" previously set up. For example, assume that the current tax rate for a city is \$5.34 per \$100.00 assessed valuation. After assessments have been made, a list showing individual assessments is sent to the tax collector's office where individual bills are typed. Each bill gives information as to the name of the person being taxed, etc., and also gives the assessed valuation. These bills are then given to an employee who extends them so that the individual taxes (in dollars and cents) may be printed thereon. Assume that the first two bills show, respectively, assessed valuations of \$5,700.00 and \$83,500.00. In extending these two bills, with the present machine, the operator first sets the total selecting lever for "transfer totals" and then sets up 534 (the "constant factor") on the digit keys and then latches down the constant-factor key. The operator then holds the multiply lever in its active position and depresses the

"7" digit key. As soon as the "7" key has risen and the machine stops cycling, the operator depresses the "5" key and releases the multiply lever. At the end of five cycles the machine stops and the upper accumulator contains the product of the factors "534" and "57" or the amount 30438. So far, no printing has taken place and no carriage return has occurred. The operator then inserts the first tax bill in the machine and strikes the "Total" palm-bar. This cycles the machine in such a manner that 30438 is printed, the upper accumulator is cleared, the total 30438 is run into the lower or grand total accumulator, and the cam carriage still retains the "constant factor" 534, and the carriage is moved from its totaling position to the exact position it assumed at the time when the operator latched down the constant-factor key. The operator then removes the first bill and proceeds to extend the second. The extending of the second bill is accomplished in the same manner as the extending of the first bill except that the multiplier used is 835 instead of the previous multiplier 57. Thus, the operator continues until all the individual tax bills have been extended. After the last extension has been completed, the operator inserts a piece of paper and moves the accumulator shift lever to the right. The "Total" palm-bar is then depressed and this causes the machine to cycle, clearing the lower accumulator, and printing the grand total. This grand total represents the amount of tax due for the entire group of bills. It is to be noted that previous to the present invention two machines were usually used in doing the above mentioned tax work. One of these machines was a high speed calculator which did not print and the other was a regular listing (printing) adding machine. The actual extension work was done on the high speed calculator and each extension had to be transcribed, by the operator, from the dials of the calculator to the tax bills. This was usually done in pencil and errors could easily have arisen in this transcribing process. After all the extensions and transcriptions were done, the entire set of (extended) tax bills was taken to the above mentioned listing machine and each extension was listed upon a continuous tape. After all the extensions had been listed, the total of the listings was printed at the foot of the tape. Thus, a chance for making errors arose during this listing operation. After listing, the bills were taken back to the high-speed non-print calculator, and the actual assessments (not extensions) shown on the bills were additively entered into its accumulator. The total of the actual assessments (in the high speed calculator) was then multiplied by the current tax rate. At the end of this operation, the operator compared the total (shown on the dials of the high-speed calculator) with the total on the listing-tape and, if these totals agreed, the operator knew that all the bills had been properly extended. Another method was to list the assessments on a separate tape and then multiply the total on this tape by the tax rate. In this way the two tapes could be compared for errors. From the foregoing it is seen that the present invention eliminates the necessity for using two machines, eliminates many of the opportunities for error offered by the previous extension system and further saves a great amount of time. Also, the present machine is a time saver because of its adaptability to "touch" operation, a type of operation which is practi-

cally impossible with any machine other than the ten-key type.

The present invention has been carefully designed throughout with the idea in mind of fool-proofing it and also with the idea of eliminating, as far as possible, the mental strains imposed upon the machine operators who might use it. In other words, the manual manipulation of the machine has been made as simple as possible so that the operator may give maximum attention to the work at hand rather than to the operation of the machine.

It is to be understood that, while an example of one particular type of work has been given, the machine is by no means limited to this usage.

In the following description the various mechanisms of the machine are suggested by a letter or letters preceding the associated reference-character digits wherein the following letters 20 suggest the following mechanisms:

A	—accumulator
AP	—actuating-plate
BS	—back-space
C	—carriage
CF	—constant-factor
E	—escapement position
F	—frame
K	—key
M	—motor
P	—printing
S	—type-sector
X	—multiply
RX	—remultiply

35 From the above, it is to be understood that a reference character, such as A378, would mean part 378 of the accumulating mechanism, etc.

One object of this invention is to provide a small, portable, printing-calculating machine, 40 which machine is easy to operate and which is inexpensive to manufacture.

Another object of this invention is to so construct and arrange the keys and mechanisms of a calculating machine that the machine may be operated by one hand of the operator and, further, that it is adapted to the touch system of operation, thus eliminating the need for highly trained operators.

Another object of this invention is to provide 50 a machine with mechanism so arranged that the handling of decimals can be simply and easily accomplished without laterally shifting the accumulators, thus eliminating confusion as to decimal point locations.

Another object of the present invention is to provide a calculating machine wherein during the accomplishment of multiplication problems, more than one factor may be introduced on the one set of digit keys.

Another object is to provide a multi-accumulator machine in which amounts may be shifted from any accumulator to any other without using the digit keys.

Another object is to provide, in a calculating 65 machine, means for printing true negative totals without the use of a "fugitive one" mechanism.

Another object of the present invention is to provide a calculating machine having "constant-factor" mechanism which mechanism permits a predetermined multiplicand to be locked in the machine for use in multiplication and which mechanism, when effective, causes an automatic carriage return, after a total cycle, to any predetermined carriage position.

Another object is to provide a small printing

calculator which is capable of high-speed operation.

Still another object is to provide a machine built with readily removable units, thus greatly facilitating repair and assembly work.

Other objects and structural details of the invention will be apparent from the following description when read in connection with the accompanying drawings, wherein

Fig. 1 is a fragmentary top plan view of the accumulator in normal position shown partly in section;

Fig. 2 is a right-hand side elevation of the accumulator in normal position showing the side wall in full and showing a portion of the right-hand supporting wall broken away;

Fig. 3 is a left-hand section elevation taken along the line 3—3 of Fig. 1;

Fig. 4 is an exploded isometric view showing the transfer mechanism of one accumulator wheel and part of the tubular casing;

Fig. 82 is a fragmentary detail view of certain parts of the re-multiplying mechanism in operated position.

ACCUMULATORS

The two accumulators of the present machine are identical in shape, size, and construction, and are arranged one under the other. Both are held in a single-piece bail-shaped frame

A14, which frame is removably mounted upon the main casting F1 by means of screws. The accumulators of the present machine are the same as those shown and described in Patent 2,203,306 issued June 4, 1940 to David Y. Read, entitled "Improvement in accumulating mechanism." The accumulators are not specifically claimed herein but, as they cooperate with the present machine, they will be described in detail.

10 Referring particularly to Figs. 1 and 9, it is seen that each accumulator assembly is mounted upon a main accumulator shaft A1. Loosely mounted upon the shaft A1 is a series of internal frames A2, spaced apart, and held against movement in any direction by three spacing bars A3 (Fig. 1) one of which is shown in detail in Fig. 10. The frames support various parts of the transfer mechanism, which will later be described in detail, and also support a tubular casing A4. 15 The casing A4 has its front portion cut away, as shown in Figs. 3 and 9, so that the forward portions of the internal frames A2 may project therethrough. The tubular casing A4 is formed (as is most clearly shown in Figs. 1 and 2) with four lugs A5 at each end thereof. These lugs have small grooves, cut in their inner edges, for cooperation with a pair of locking plates A6. There is one locking plate A6 at each end of the casing A4 and these plates are each formed with four high parts A7, a forwardly extending arm A8, and an upright arm A9. Each upright arm A9 is formed, at its top, with an offset lug which is adapted to engage in a slot A10, cut in the accumulator side plates A11. The side plates A11 and locking plates A6 have similar slots A12 cut therein to allow the accumulator shaft A1 to project at each end. The lugs A5, on casing A4, extend through slots in the side plates A11. In assembling, the side plates A11 are slipped over the lugs A5 and shaft A1 and the locking plates A6 are then placed flat against the side plates A11 at a radial angle of approximately forty-five degrees variation from the position shown in Fig. 2 so that the high parts A7 of the locking plates A6 are all aligned with the grooves in the lugs A5. The locking plates are then given an eighth of a turn clockwise, as seen in Fig. 2, to position them as shown. Here the lugs on the upright arm A9 engage in the slots A10 and thus 20 lock the accumulator side walls A11 to the casing A4. Loosely mounted upon the casing A4 is a plurality of accumulator wheels A13 which wheels combine the functions of visible dials and accumulator pinions as will later be described in detail. A bail-shaped accumulator frame A14 (Figs. 2 and 22) having side walls A15 is mounted upon the main casting F1 and each wall A15 has cut, therein, grooves A16 (Figs. 1 and 22) which run rearwardly in the side walls. The grooves A16 support and guide the movement of the main accumulator shafts A1. 25

20 The bail-shaped accumulator frame A14 (Figs. 2 and 22) having side walls A15 is mounted upon the main casting F1 and each wall A15 has cut, therein, grooves A16 (Figs. 1 and 22) which run rearwardly in the side walls. The grooves A16 support and guide the movement of the main accumulator shafts A1.

25 A pair of screws A17 extend through each of the frame walls A15 and directly into the groove A16. These screws A17 limit the forward and rearward sliding motion of bars A18 which run laterally across the entire accumulator unit. The bars A18 extend through slots in the accumulator side plates A11 and, as is best seen in Figs. 1 and 2, they have small notches A19 cut in their 30 rear edges to receive the arms A8 of the locking plates A6. Pairs of springs A20 tend, constantly, to urge the accumulator shafts A1 toward the bars A18. It is thus seen that, if the accumulators are moved forward or rearward in the frame walls A15, the bars A18 must move with

them and that the rearward movement of the accumulators will be limited by the screws A17.

As is best shown in Figs. 1, 2, and 22, the actuating mechanism for the accumulator wheels consists of a series of swinging sectors S to which are riveted a plurality of type-bearing rack segments S1. The accumulator is pushed into and out of engagement with the segments S1 by means to be later described in detail under the heading Accumulator engaging and disengaging mechanism. Shafts A22 extend through both frame walls A15 and are milled out along their middle portions. Secured to these milled faces are U-shaped bars A23 which bars are bent up at each end into a pair of arms A24. These arms are formed with slots A25 (Fig. 2) cut therein and these slots receive opposite ends of the accumulator shafts A1. Thus, when the shafts A22 are turned they will function to move the accumulators into and out of mesh.

To accumulate positive amounts, the actuating racks S1 are swung up to various positions by mechanism which is later described in detail under the heading "Carriage and cams" and the wheels A13 are then thrown into mesh. The racks are now moved down to their normal positions thus turning the accumulator wheels in a clockwise direction (Fig. 2) as is old and well known.

In order to subtract, the racks S1 are left at normal and the accumulator is thrown into mesh. Subsequent raising of the racks will then turn wheels A13 in a counter-clockwise direction, as seen in Fig. 2.

TRANSFER MECHANISM

With particular reference to Figs. 1 and 5, it is seen that each accumulator wheel A13 has cut therein, an annular groove A30. Each wheel A13 has a raised block A31 upon its periphery which block has, inscribed thereon, the numeral "1". Through this block A31 there extends inwardly a pin A32 (Fig. 5) and this pin lies directly within the annular groove A30. In the adding and subtracting position of the accumulators, which is shown in Fig. 5, a transfer-trip member A33, having a nose A34 thereon, lies in such a position that the nose A34 protrudes toward the front of the accumulator and lies within the annular groove A30 of the accumulator wheel of the next lower order. That is to say, the transfer-trip A33, for a tens order accumulator wheel, lies with its nose A34 in the groove A30 of an accumulator wheel of the units order.

From the foregoing, it is evident that as the pin A32, on any accumulator wheel, passes its associated nose A34, in either direction, it will cam the nose out of the groove A30 and push the transfer-trip A33 toward the accumulator shaft A1 (see Fig. 6).

As was previously mentioned, a series of internal frame walls A2 support the transfer mechanisms and the relation of these walls to the accumulator wheels A13 may be easily seen from Figs. 1 and 9. With particular reference to Figs. 3 and 4, it is seen that, in the normal position (Fig. 3) or the position of rest of the accumulators, the shafts A1 lie in their foremost positions in slots A35 which slots are formed in the frames A2. Loosely mounted upon each shaft A1, is a plurality of detents A36 which engage in openings A37 in the accumulator wheels A13. Each transfer-trip A33 is formed with a pair of pins A38 thereon. These pins A38 extend both rightwardly and leftwardly from the trips A33. 75

The rightwardly extending portions are supported and guided by a pair of slots A39 in the frames A2. The leftward portions of pins A38 extend through a pair of detent guides A40 and form pivots for these guides. Extending from the left-hand side of each of the transfer-trips A33 is a lug A41 (Fig. 4) which lies adjacent the detent A36 and holds it flush against the frame A2.

10 The guides A40 are formed with raised portions A42 which lie flush against the internal frames A2. The guides A40 are each equipped with a coiled spring A43 as is shown in Fig. 3. The springs A43 normally hold the guides A40 and the trip members A33, upon which the guides are mounted, in the Fig. 3 position.

A restoring member A44 (there is one for each trip member) is made with two rightwardly extending pins A45 (Fig. 3) thereon. These pins A45 are shown dotted in Fig. 3 and they extend into guide slots A46 in the frames A2. Extending leftwardly (Fig. 4) from each restoring member A44 is a pair of lugs A47 the functions of which will be later described in detail.

TRANSFER OPERATIONS

In actuating either accumulator during adding or subtracting operations, the entire accumulator unit is moved rearward by shaft A22 (see Figs. 1 and 2) until the bar A18 rests against the rear studs A17. At this time the teeth of the segments S1 are in mesh with the openings A37 in the wheels A13. The shaft A22 is rotated slightly farther and this brings the accumulator

35 shaft A1 from its normal position shown in Fig. 3, to the position shown in Fig. 5 wherein the shaft A1 lies in the extreme rear ends of the slots A35. This releases the accumulator wheels from the detents A36 and leaves the wheels free

40 to be turned by the segments S1. Preparatory to moving the accumulator wheels out of mesh with the segments S1 the shaft A1 is moved toward the front of the accumulator until the detents A36 engage in their respective slots A37.

45 At this time the wheels A13 are still in mesh but, as the shaft A1 continues to move forward, the wheels are pulled out of mesh and continue forward until the bar A18 (see Fig. 1) comes to rest against the forward studs A17 as shown.

50 Referring particularly to Figs. 5 to 8, inclusive, Fig. 5 shows the parts as they normally stand when the wheels A13 are in mesh with their actuating racks. In this position, it will be seen that the rear parts of the detents A36 lie midway between the lugs A47 on the restoring members A44.

55 Assume, for example, that in Fig. 5 all the wheels A13 of one of the accumulators are standing in their cleared position. Assume further that

60 "1" is now subtracted from the wheel of units order. This moves the wheel of units order to the Fig. 6 position. In this view the block A31 of the tens order is shown in dot and dash. As the wheel moves from the Fig. 5 position to the Fig.

65 6 position, the inwardly extending pin A32 thereon cams the nose A34 of the tens order wheel clockwise about the upper pin A38. This moves the lower pin A38 rearward in its slot and snaps over the lower spring A43 which then forces the nose of the lower guide A40 into a groove A49 which groove is cut along the entire length of the tubular casing A4. There is also an upper groove A49 for the upper guide A40. The rearward movement of the lower guide A40 causes its rear part to push against the restoring member

A44 and swing this member clockwise about a point **A50**. This brings the upper lug **A47**, thereon, to a place where it is almost contacting a rear edge **A51** on the detent **A36**. The upper lug **A47** now acts upon the edge **A51** to support the detent **A36**.

The description, given thus far, has covered the actions of the transfer parts of the tens wheel from the beginning to the middle of a carry or transfer cycle. In the second half of the transfer cycle, the accumulator shaft **A1** moves forward in the accumulator until it assumes the position shown in Fig. 7. All the parts, when once moved to the Fig. 7 position remain there for the rest of the cycle. As the detent **A36** moves forward (Fig. 6), in the second half of the transfer cycle, its point first enters the opening **A37** which is directly in line with it and, as the shaft **A1** and detent **A36** continue their forward motion, an ear **A52**, on the detent **A36** of tens order, contacts the lower pin **A38**. As the nose of the lower guide **A40** is now being pressed by spring **A43** into the lower groove **A49**, the pin **A38** will not move. However, the shaft **A1** still continues its forward motion, and ear **A52** being held by pin **A38**, the result is that the detent **A36** is cammed clockwise about the shaft **A1**. This rotates the tens order wheel **A13** one tooth space clockwise. Shortly after the tens order wheel begins its rotation of one tooth space, the pin **A32**, extending therefrom, contacts the nose **A34** of the transfer-trip member **A33** corresponding to the hundreds order wheel and cams it about its upper pin **A38**. This moves its lower pin **A38** rearward in its slot until it meets the ear **A52** of the forwardly moving hundreds order detent **A36**. Continued rearward movement of the pin **A38** and forward movement of the detent causes the detent to rotate clockwise about its pivot **A1**. As the point of the detent has entered the opening **A37** of the hundreds order wheel **A13** by the time the pin **A38** meets the ear **A52**, it will be seen that the clockwise rotation of the detent will move the hundreds order wheel one tooth space clockwise. In the same manner transfer takes place in the wheels of higher orders by the time the shaft **A1** has reached its extreme forward position. Thus, at the end of the forward movement of the shaft **A1** every accumulator wheel will have moved one space and the accumulator wheels will read 99999 etc., instead of 00000 etc.

As the accumulator wheels are still in mesh when the transfer operation attempts to rotate them, it is seen that the actual rotation of the wheels is started while they are still in mesh but is completed afterwards. Due to the fact that a transfer is completed while the accumulator is being drawn toward its normal position or position of rest, a great amount of speed is gained.

The various parts of the transfer mechanism are restored to normal position on the next cycle which follows a transfer cycle. In a restoring cycle (after a tens-carry) the shaft **A1** moves toward the rear of the machine as it would at any time that the accumulator was being meshed with the actuating racks. As the shaft **A1** moves rearward within the accumulator, the upper heel **A53** of the detent **A36** contacts the upper lug **A47** on the restoring member **A44** and swings the member **A44** about its pivot point **A50**. In the first part of its counter-clockwise movement, a cam edge **A54** on the member **A44** acts upon the rear point of the lower guide **A40** and cams the guide slightly counter-clockwise about its pivot pin **A38** so that the forwardly extending nose 75

of the guide no longer rests in the groove **A49**. Fig. 8 shows the parts just after the shaft **A1** has started rearward in a restoring cycle. Continued motion of the restoring member **A44** pushes the lower guide **A40** to a place where the spring **A43** takes effect to move the guide to its normal position with a snap. This movement of the guide **A40** causes its raised portion **A42** to engage the under side of its associated detent **A36**, which lies in the same plane, and raise said detent, about its shaft **A1**, to its normal position. While I have called the above cycle a restoring cycle, it is to be understood that restoring occurs at the first part thereof and that regular addition or subtraction may be accomplished in this cycle as in any other.

While transferring was herein described in connection with subtraction, it is evident that the transfer in addition will be the same except that 20 the wheels **A13** will then be turned in the opposite direction.

ZERO-STOPS

Referring to Figs. 1 and 2, a zero-stop **A60** 25 formed as shown extends laterally in front of the accumulator wheels **A13** and is cradled in the accumulator side plates **A11**. A spring **A61** (Fig. 2) tends constantly to urge the zero-stop **A60** counter-clockwise. Loosely mounted upon 30 the shaft **A22**, near its right-hand end, is a forwardly extending lever **A62** which has a rightwardly bent-over end **A63**. This end extends through a slot in the right-hand wall **A15**. The lever **A62** has a slot **A64** near its middle and a 35 large headed screw **A65** (see Fig. 1) extends through this slot and into the wall **A15** thus holding the lever against lateral movement on the shaft **A22**.

To clear the machine, the accumulator is 40 moved into mesh with the actuating racks. The lever **A62** is swung clockwise as seen in Fig. 2 thus moving the zero-stop **A60** clockwise into the path of the lugs **A31** on the accumulator wheels **A13**. The sectors **S** are then moved upward until 45 all the lugs **A31** contact and are stopped by the zero-stop **A60**. The accumulator is then moved out of mesh and is in cleared condition.

MAIN CASTING AND KEYBOARD

50 All the mechanism units of the present machine are mounted, upon a main casting **F1** (see Figs. 11, 13, and 14). Each unit is made so that it can be removed from the casting **F1**, the mechanisms having been designed so that most of the 55 units can be removed without removing any others. Stated broadly, each unit consists of framing and a particular mechanism or mechanisms mounted thereupon. As is seen in Figs. 13 and 23 the main casting **F1** runs from front to rear 60 of the machine. This casting is recessed, at its front end to accommodate the palm bars, correction key and accumulator shift key. Casting **F1** is formed, at its rear end, into a cylindrical shape with a reinforcing rib **F2** on each side. Upon the 65 left-hand rib **F2** (Fig. 14) is removably mounted an arm **F3**, and this arm carries on its lower end a rod or shaft **F4**, upon which a tally roll may be mounted. When it is desired to print with this machine upon large papers such as ledger sheets, etc., the arm **F3** is removed from the machine and the paper is inserted into the opening **F5** through a throat **F6**. Rolls **F7**, of any suitable construction may be used to hold the paper in place. The rolls **F7** are not shown in detail in 70 the present drawings nor is any paper-feed mech-

anism shown as these things form no part of the present invention. It is to be noted, here, that the rolls F7 can be arranged with a device for separating them at the will of the operator, so that bills, etc., could be easily inserted through the throat F8. After the bills are adjusted, the operator can retension the rolls F7 to hold the paper for printing and line spacing, etc.

Referring particularly to Fig. 11, it will be noted that six keys are located at the front of the machine. The leftmost key K1 is the accumulator-shift key. Next, to the right, is the subtract palm-bar K2. Next to this lies the add palm-bar K3. Beneath the right-hand side of the palm-bar K3 is the correction key K4. Just to the right of K4 is the total palm-bar K5. Directly beneath the right-hand side of the palm-bar K5 is the total-selecting lever K6 (see Fig. 44). Near its middle, the casting F1 (Fig. 11) supports a removable keyboard plate F8 through which the stems of the ten digit keys project. The "0" digit key-cap is formed with a rib along its right-hand side so that it may be used as a guide key in touch operation of the machine. At the front of the plate F8, and near its left-hand side, an ear F9 (Figs. 11 and 64) is bent down and upon this ear is pivoted a multiplication key or lever K7 and a cooperating bell-crank K8. In the center of the plate F8 is fastened a back space or point off key K9 and its housing. Just to the right of K9 there is, projecting through the keyboard plate F8, a constant-factor key K10. Behind and slightly to the left of the key K10 is a remultiply key K11 and behind this is a grand-remultiply key K12. The rearmost key in the machine is the printing-control key K13. The keyboard plate F8 is held in place by screws F10 (Fig. 11) which thread into lugs F11 (Fig. 23), the lugs F11 being formed integral with the main casting F1. Referring particularly to Fig. 23, it is seen that a key-hanger F12 has two rearwardly extending fingers F13. These fingers are fastened to the digit keyboard-plate F8 by any suitable means such as rivets, spot-welds or screws. Also secured to the plate F8 is a bracket F14 for a ball-lock and this is shown, in right-hand elevation, in Fig. 18. The bracket F14 is slotted to permit the passage, therethrough, of the stems of the digit keys. Referring to Figs. 12 and 18, it is seen that, at its forward end, the key-hanger F12 is bent so that it forms a slotted sleeve which holds a rod F15 (Fig. 18). The rod F15 passes through holes in the digit key-levers and thus the key levers are pivoted upon the rod F15 and are spaced apart, at their forward ends, by the slots in hanger F12. The key-levers are spaced and guided, at their rearward ends by the slots in the bracket F14. The keys are constantly urged upward by contractile springs K16 (Fig. 12), which are anchored in holes in the key-hanger F12 and to the bottoms of the digit keys.

From the foregoing it is seen that the digit keys and their associated ball-lock can be removed from the machine by merely removing the keyboard plate F8. The ball-lock is for the usual purpose of safeguarding the machine against depression of more than one digit-key at a time. Although no means is herein shown for adjusting the spacing of the balls, it is obvious that any of the well known adjusting means could be used.

MOTOR DRIVE AND ACTUATING PLATES

The present machine is designed to be driven by a small motor which can be either continu-

ously operated or which can be started by the motor-control keys of the machine. In the present instance, a continuously operated motor is used. This motor, through a single-revolution clutch and pitman, drives one or another of a series of actuating plates shown individually in Figs. 26 and 28 to 37, inclusive.

Referring particularly to Figs. 20 and 24, it is seen that the motor M is suspended from a horizontal cross-brace F16 which runs laterally in the machine near the front. The cross-brace F16 is screwed, at F17, to an upright motor frame-wall F18 (shown in left-hand elevation in Fig. 14) and is fastened by screws F20, at its right-hand end, to an upright motor frame-wall F19 (Fig. 24). This right-hand motor-frame wall is shown in right-hand elevation in Fig. 13. The motor shaft M1 has, fast to its right-hand end (Fig. 24) a gear M2. This gear M2 constantly meshes with a gear M3 which is fastened by a hub M4 to a gear M5. The hub M4 and gears M3 and M5 turn in unison and are pivoted upon a shouldered screw (not shown) which is fastened into the heavy frame wall F18. The gear M5 is in constant mesh with a gear M6. The gears M2, M3, M5, and M6 constitute a reduction gearing. The gear M6 is fast on a hub M7 which passes through the wall F19 and, as is best seen in Figs. 15 and 24, is fastened at its right-hand end to a ratchet M8. Referring to Figs. 13, 15, and 24 it will be seen that the ratchet M8 is positively driven, at reduced speed, by the motor M. Loosely mounted upon hub M7, between the wall F19 and the ratchet M8, is a clutch disk M9. This disk is fastened to a segmental drive-plate M10 by means of screws M11. The clutch disk M9 is spaced from the plate M10 by spacers M12. Pivoted upon the right-hand side of the drive-plate M10 is a pitman M13 the rearwardly extending end of which is pivotally supported, by a counterbored screw, upon the vertical right-hand portion of a U-shaped pitman bracket M14. The pitman bracket M14, referring particularly to Figs. 18 and 19, has a left-hand upwardly extending side-portion M15 which lies flush against the inside of the right-hand wall of a single-piece actuating-plate-frame F22. The left-hand side portion M15 of the pitman bracket M14 has cut therein, near its front end, a slot M16 (Fig. 18) which slot rides a horizontal cross-bar F23 of the actuating plate frame F22. A keeper F24 holds the pitman bracket M14 against the inside of the frame F22 (see also Fig. 63). Near its middle, the portion M15 of the pitman bracket M14 is bent leftwardly to form a driving arm M17. This arm extends across all the actuating-plates and is the means by which they are driven. The portion M15 is also slotted (Fig. 18) near its rear end at M18. A thin-headed rivet M19 holds the portion M15 of the pitman bracket M14 against the actuating-plate frame F22 and, cooperating with slot M18, serves to further guide the bracket M14.

The actuating-plate frame F22 includes a large upright portion F26 which is bent off, at its top, toward the left-hand side of the machine into a lug F27. The lug F27 is fastened to the main casing F1 by means of screws F28 (Fig. 19). Near its rear end, the portion F26 is formed into a rightwardly extending lug F29 which is fastened to a boss on the cylindrical portion of the main casting by a screw F30. The forward end of the frame F22 is U-shaped and is mortised at points F31 in a downwardly bent flap F30 of the

motor cross-brace F16 (see Fig. 18). Referring to Figs. 20 and 23, it is seen that the left-hand upright portion of the frame F22 extends rearwardly only about one third the distance of the right-hand upright portion. From Figs. 18 and 23, it is seen that the upright side-portions of frame F22 are held together by shouldered countersunk screws F32 and F33 and are spaced apart by the horizontal cross-brace F23 and a vertical cross brace F34. Mortised in the portion F26 of frame F22 is a small vertical brace-bar F35 (see also Fig. 19) which is cut out along its middle portion to receive and guide the actuating-plates. At its rear end, the frame F22 holds a shouldered screw F36 which screw passes through slots in the rear ends of the actuating-plates and thus supports and guides them. A collar F37 (Fig. 19) serves to keep the rear ends of the actuating-plates together and spaced from the frame F22 so that the pitman-bracket M14 can move without interference.

Referring particularly to Figs. 18 and 20, it is seen that the actuating-plates AP1 to AP11 are arranged with their tails pointing toward the front of the machine and their functions, generally will now be described.

The plate AP1 (Fig. 26), nearest the left-hand side of the machine, is the multiplication actuating-plate and its function is to mesh and unmesh the upper accumulator to cause repeated adding, therein, during multiplication machine cycles.

Each actuating-plate is adapted, after its tail has been raised, to engage the leftwardly bent arm M17 of the pitman bracket M14 and to be driven by the arm M17 toward the rear of the machine (on what will hereafter be known as the "forward" stroke) and then positively driven to its initial position (on what will hereafter be known as the "return" stroke). Every plate AP, except the multiplication plate AP1, will cycle the machine, by causing engagement of the single-revolution clutch, when its tail is lifted as will be explained in detail hereinafter.

To continue with the functions of the actuating-plates, the plate AP2 is the correction plate. This plate, when its tail is lifted, will cycle the machine and will clear out any amount previously set up in the cam carriage, will cause the return of the carriage to home position, and will not move, either accumulator, into or out of mesh.

AP3 is the addition plate and this, when its tail is lifted, will cycle the machine, throw the upper accumulator into mesh with the rack-segments at the end of the forward stroke, unmesh the upper accumulator near the end of the return stroke, and will clear the cam carriage and cause its return to home position.

AP4 is the subtraction plate and this plate, when its tail is lifted, will cycle the machine, throw the upper accumulator into mesh at the beginning of the forward stroke, throw the upper accumulator out of mesh near the end of the forward stroke, clear the cam carriage and cause its return to home position.

AP5 is the grand-addition plate and this plate, when its tail is lifted, will cycle the machine, throw the lower or grand-total accumulator into mesh at the end of the forward stroke, throw the grand-total accumulator out of mesh at the end of the return stroke and will clear the cam-carriage and return it to home position.

AP6 is the grand-subtraction plate and this, when its tail is lifted, will act upon the lower accumulator in the same manner that AP4 acts

upon the upper accumulator causing clearing and return of the cam carriage.

The following five actuating-plates have to do with various kinds of totals and for this reason 5 they are shaped to accomplish extra functions. To avoid repetition, in the following description, it is to be understood that each of the plates AP7—AP11 (inclusive) causes the cam carriage to be drawn from its home position to its extreme right-hand position at the beginning of the forward stroke and causes carriage return (from right to left) near the end of the return stroke. Also, each of these five plates, on the forward stroke, will cause swinging of the type sectors which sectors will be automatically returned independent of the actuating-plates.

AP7 is the sub-total taking actuating-plate and is associated with the upper accumulator only. This plate will cycle the machine, throw the upper accumulator into mesh at the beginning of the forward stroke, and throw the upper accumulator out of mesh near the end of the return stroke.

AP8 is the grand-sub-total taking actuating-25 plate and is associated with the lower accumulator only. This plate will act to cause sub-totaling in the lower accumulator in the same manner as AP7 acts upon the upper accumulator.

AP9 is the transfer-total plate. This plate will 30 cause totals, accumulated in the upper accumulator, to be transferred to the lower accumulator. At the beginning of the forward stroke, the upper accumulator will be meshed with the rack segments; at the end of the forward stroke the upper accumulator (cleared) will be thrown out of mesh and the lower accumulator will be thrown in. At the end of the return stroke, the lower accumulator will be thrown out of mesh and thus a total will have been transferred.

AP10 is the total taking actuating-plate and is associated with the upper accumulator only. This plate, when active, will throw the upper accumulator into mesh at the beginning of the forward stroke and will throw it out of mesh near the end of the forward stroke.

AP11 is the grand-total taking actuating-plate and is associated, only, with the lower accumulator. This plate will mesh and unmash the lower accumulator in a manner similar to that described in connection with AP10.

The machine is cycled by engagement of a single-revolution clutch and it is to be understood, at this point, that one cycle of the machine consists of driving the pitman bracket M14 toward the rear of the machine and back to its normal position and it is to be further understood that regardless of the clutch-control mechanism used, the cycling of the machine always includes the above driving of the pitman bracket M14.

The various controls for lifting the tails of the actuating plates to cycle the machine will now be described except for the multiply key K7 and the remultiply key K11. These two keys have specialized motor-control functions and they will be described, in detail, under the headings Multiplication and division and Remultiply mechanism, respectively. The regular motor-control means of the present machine are best shown in Figs. 15, 20, and 38-42, inclusive.

Referring to Fig. 15, the single-revolution clutch-disk M9 has, pivoted thereupon, a clutch pawl M22. A spring M23, anchored at its front end to the pawl M22 and at its rear end to one of the screws M11, tends constantly to draw the pawl M22 into engagement with the teeth of the

ratchet M8. The pawl M22 is formed with a forwardly projecting tail M24. The pawl M22 is held in its normal or Fig. 15 position, in which it is disengaged from the teeth of the ratchet M8, by means of its tail M24 engaging a rearwardly bent ear M25 (see Figs. 15 and 38) formed on a rightwardly extending branch of a motor-control bail M26. The motor control bail M26 is pivoted, at its right-hand end, upon the motor frame-wall F18 by means of a shouldered screw M27 which passes through a hole in a rearwardly bent portion M28 of the motor-control bail M26. With particular reference to Figs. 38 and 40, it is seen that the motor-control bail M26 is formed, near its middle, with a rearwardly and downwardly extending flap M29. The left-hand end of the bail M26 is bent rearwardly into an upright portion M30 which is notched at M31 to receive one end of a toggle spring M32 (Fig. 40) the other end of the spring being anchored in a hole in the frame wall F18. The portion M30, of bail M26, is fastened by screws M33 to a disk M34. This disc is journaled in a hole in the left-hand motor frame wall F18 (see Figs. 14 and 38). The disk M34 may be easily made by merely stamping it out of the wall F18. The portion M30, of bail M26, is slightly offset near its middle to provide an anchorage for the spring M32. Thus, whenever the bail M26 is rocked slightly counter-clockwise (Fig. 40), the toggle spring M32 takes effect and swings the bail M26 to its Fig. 41 position, thereby removing the ear M25 (Fig. 15) from the path of the clutch-pawl M22 and permitting the pawl to snap into the teeth of the ratchet M8. Means are provided for tripping the bail M26 and for restoring it to its normal position before the end of any machine cycle and these means will now be described. The normal position of the actuating-plates is shown by the plate AP10 in Fig. 40. Pivoted upon the screw F32 is a motor-control rocking-plate M35. This plate is constructed as shown in Fig. 39 and is mounted at the front end of the actuating-plate frame. A spring M36 (Fig. 18), anchored at one end to a rearwardly extending arm of the rocking plate M35 and at its other end to the actuating-plate frame F22, tends constantly to hold the rocking-plate M35 in its normal position (Fig. 40).

Referring particularly to Figs. 40, 41, and 42, the parts of Fig. 40 are all in normal or un-operated position. Whenever any of the tails of the actuating-plates (except the multiply plate AP1) are lifted, they assume the position shown in Fig. 41 wherein the plate AP10 has been lifted but has not yet begun its forward stroke (rearward movement in the machine). In rising, the actuating plate tails contact a portion M38, of the rocking plate M35, which (see Fig. 38) overlies all the tails. Thus, the rocking plate M35 is swung counter-clockwise to its Fig. 41 position and, in being so swung, a forwardly extending arm M39, thereof, contacts the flap M29 of the motor-control bail M26 and moves the bail counter-clockwise to permit engagement of the motor clutch pawl M22. As soon as any actuating plate has been lifted to the Fig. 41 position, it has become fully engaged with the arm M17 (Figs. 19 and 20) of the pitman bracket M14 and thus, as the pitman bracket M14 moves rearward and forward, the actuating plate is positively driven with it in both directions, it being understood that the actuating-plates are guided, in their sliding movements, by the horizontal crossbar F23 and the shouldered screw

F36 (Fig. 20). At this point, it is to be noted that the flap M29 (Figs. 38 and 40-42) has been designed so that the motor-clutch will not be tripped unless the actuating-plate tail has been fully lifted to its Fig. 41 position. From a study of Fig. 41, it is seen that, when an actuating plate has been fully lifted, the rearmost part of flap M29 lies directly under a tip AP27 of the actuating plate. If the actuating-plate has not been fully raised, then either the arm M39 of the rocking-plate M35 will not contact the flap M29 at all or if it does, it will only move the motor control bail a very slight amount about its pivot points and cause the rear end of flap M29 to hit the surface AP28 of the actuating-plate tail. Such an amount of movement of the motor-control bail M26 is not enough to trip the motor-clutch pawl M22 (Fig. 15). Each actuating-plate, except the multiply plate AP1, restores the motor control bail M26 on its return stroke. As is seen in Fig. 42, the actuating plates, on their return strokes, contact the portion M38 of the rocking plate M35, it being understood that the rocking plate returns, under tension of the spring M36, to its Fig. 40 position as soon as the actuating-plate tails release it on their forward strokes. The returning actuating-plates swing the rocking-plate M35 clockwise, as seen in Fig. 42, so that the part M38 contacts the flap M29 of the bail M26, and swings the bail clockwise a certain distance. As it is necessary that the portion M38 be of such length that it just clears the tails of the unlifted actuating plates when the rocking plate is swung clockwise (Fig. 42), the plate M35 is made with a slight extension M42 (Fig. 39). Therefore, continued rotation of the rocking plate M35 causes its extension M42 to contact the flap M29 and move the bail M26 until the ends of the toggle spring M32 are forced past center. The toggle spring then takes effect and fully restores the motor-control bail M26. The timing is such that the motor-control bail is fully restored before the tail M24 (Fig. 15), of the clutch pawl M22, contacts the ear M25. From the foregoing, it is understood how the actuating-plates trip and restore the motor-control bail M26 and it is to be noted that the rocking plate M35 will not return to its Fig. 40 position until after the tail of the actuating-plate has dropped.

The means for raising the tails of the actuating-plates (other than the means used in connection with the multiplication and re-multiplication mechanisms) are best shown in Figs. 20, 24, 25, 43, and 44 and will now be described. With particular reference to Figs. 24, 25, and 44, it is seen that there is a frame plate F40 which runs laterally across the front of the machine. This frame plate is fastened, in the present instance, by countersunk screws F41 (Fig. 15) to the right-hand motor frame-wall F19 and is fastened by countersunk screws F42 (Fig. 14) to the left-hand motor frame-wall F18. The frame plate F40 is recessed, along its mid-portion to admit the accumulator-shift key K1. This key is preferably made as a single-piece die stamping and is of the same thickness as the frame plate F40. The key K1 is mounted for sliding movement in the recess cut in the frame plate F40. The palm bars K2, K3, and K5 are held against the rear side of the frame plate F40 by headed rivets F43 which pass through slots F44 in the palm bars. Thus, the palm-bars help to hold the key K1 in place. The palm bar K2 is guided for vertical sliding movement by the

right-hand side of its associated recess in the main casting F1 (Fig. 25) and by its rivet F43 and a small pin F45 (Figs. 24, 25, and 44) which pin is secured in the frame plate F40. The palm bar K5 is guided for vertical sliding movement by its rivet F43 and by its associated recess in the main casting F1. In this instance, no bottom guide pin, such as pin F45, is necessary as the main-casting recess is the same width as the key K3 (see Fig. 25). The palm bar K5 is guided for vertical sliding movement by its rivet F43, its associated recess in the main casting and by a pin F46, secured in the frame plate F40. The correction key K4 is pivoted upon a T-shaped rivet (Figs. 25 and 44) F47 which is secured in the upper part of the frame plate F40. The total-selecting lever K6 is pivoted upon the rivet F43 which is associated with the palm bar K5. Referring particularly to Figs. 24 and 25, it is seen that a rock-shaft K18 runs from side to side of the motor framing near the bottom and front of the machine. The shaft K18 is journaled, at its right-hand end in the heavy motor frame-wall F19. At its left-hand end, the shaft K18 is journaled in a hub F48 which is riveted to the frame wall F18. The rock-shaft K18 is adapted for longitudinal sliding motion as well as for rocking motion. For this reason, the hub F48 is counterbored so that it acts not only as a journal but also as an end-stop limiting the leftward motion of shaft K18. Normally the shaft is spring tensioned so that it rests in its leftmost position as will be explained in detail later. Referring to Figs. 24, 25, and 44, a forwardly extending arm K19 (underlying the palm bar K2) has its rear portion bent around the shaft K18 and is rigidly secured to the shaft by rivets or any other suitable means. Adjacent the arm K19 is a wide forwardly extending lever K20 which has its left rear portion bent around the shaft K18. Its rightmost rear portion is bent as shown to form an actuating-plate lifting-arm K21 (Fig. 44). The lever K20 is loosely mounted upon shaft K18. Adjacent the lever K20 is a rearwardly extending arm K22. This arm is rigidly secured to shaft K18 by means of rivets and thus, whenever the shaft is rocked, the arm K22 is rocked. The arms K22 and K19 prevent the lever K20 from moving laterally with relation to shaft K18. Nearest the right-hand end of shaft K18, is loosely mounted a lever K23 which has a rearwardly extending lifting-arm K24. The lever K23 is held against the bottom of the palm bar K5 by means of a spring K25 which is anchored at its upper end to an anchor pin K26, integral with the rivet F43, and which spring is anchored, at its lower end, in a hole in the lever K23. The spring K25 also holds the total key K5 in its up or normal position. The lever K23 is slotted at K27 to receive the downwardly extending end K28 of the total-selecting lever or key K6. The key K6 is made of a suitable springy metal and is bent at K29 (Fig. 44) to form a convenient finger-piece. A rearwardly bent portion K30 forms a tooth or catch which is for engagement with one or another of four teeth K31 (Fig. 25) formed in a small plate K32 which is screwed or otherwise suitably fastened to the main casting F1. The total-selecting lever K6 is set to one of four positions by pressing the finger-piece K29 against the palm bar K5, then moving the lever K6 about its pivot to position its tooth K30 relatively to one of the four teeth K31, and then releasing the finger-piece K29. Due to the fact that the lever K6

is rearwardly offset near its middle, the lever normally engages one or another of the teeth K31 and by pressing the lever K6 toward the palm bar K5 the tooth K30 is withdrawn from the teeth K31 to allow it to be moved about its pivot. A spring K37, anchored at one end in a hole in the lever K23 and anchored at its other end in a hole in the lever K20, tends constantly to draw the lever K23 toward the lever K20, it being understood that lever K23 is movable laterally along shaft K18 as well as pivotally about it. Thus, whenever the total-selecting lever K6 is swung about its pivot, the lever K23 follows the movement of the downwardly extending portion K28 and in so doing the lever K23 is moved bodily along the shaft K18. In Fig. 24, the actuating-plates AP1 to AP11 are diagrammatically shown. From this view it is seen that, when the total selecting lever is in its perpendicular position, the lifting-arm K24 of lever K23 underlies the tail of the total actuating-plate AP10. It is also to be noted, at this point, that the lifting arm K22 underlies the tail of the subtract actuating-plate AP4 and the lifting arm K21, of lever K20, underlies the tail of the add actuating-plate AP3. Thus, depression of the palm bar K2 turns shaft K18 raising the lifting-arm K22 and lifting the tail of the plate AP4 so that the machine is cycled for subtraction. Depression of the palm bar K3 moves the lever K20 about shaft K18, raising the lifting-arm K21 and lifting the tail of the plate AP3 so that the machine is cycled for addition. Depression of the palm bar K5, when the total-selecting lever K6 is in its vertical position, moves the lever K23 about shaft K18 raising the lifting-arm K24 and lifting the tail of the plate AP10 so that the machine is cycled for a total operation. If the total-selecting lever K6 is set one tooth-space clockwise from its Fig. 25 position (its vertical position) then the lifting-arm K24 will underlie the tail of plate AP9 and subsequent depression of bar K5 will cycle the machine for a transfer-total operation (upper accumulator to lower). If the total-selecting lever is set two tooth-spaces clockwise from its Fig. 25 position and the palm bar K5 is depressed, then the tail of plate AP8 will be raised and a grand sub-total operation will ensue (lower accumulator only). If the total-selecting lever K6 is set three tooth-spaces (its maximum setting) from its Fig. 25 position and the palm bar K5 is depressed, then the tail of plate AP7 will be raised and a sub-total operation will ensue (upper accumulator only). With reference to Figs. 24, 25, and 44, a spring K33, anchored at its upper end to a lug struck out of the frame plate F40 and anchored at its lower end in a hole in the lever K20, holds the palm bar K3 in its up or normal position. A spring K34, anchored at its upper end to a lug struck out of the frame plate F40 and anchored at its lower end in a hole in the lever K19, holds the palm bar K2 elevated. A spring K35, anchored at one end in a hole in the lever K19 and anchored at its other end to the frame wall F18 (see Fig. 25), tends constantly to hold the shaft K18 in its normal or leftward position. A spring K36, anchored at one end to a lug struck out of the accumulator-shift key K1 and anchored at its other end in the left-hand motor frame-wall F18, tends constantly to maintain the shift key K1 in its leftmost or normal position (Figs. 25 and 44).

At this point it is to be noted that the ma-

chine will be cycled only once for one depression of a palm bar and it is to be further noted that if any palm bar is depressed and held depressed the motor clutch will be disengaged from the motor and will not be reengaged until the palm bar is allowed to rise and is again depressed.

The accumulator-shift key K1 has a rather complex shape and this key and its operations will now be described in detail. The key, preferably made as a single-piece die stamping, has formed, thereon, an upwardly extending thumb-piece which, in the machine, lies at the extreme left (see Fig. 25). The central portion K38 of the key is made in the shape of an oblong bar (see Figs. 25 and 44). Offset rearwardly from the portion K38 is a downwardly extending arm K39. The arm K39 branches out, at its bottom into a pair of legs K40 and K41. The leg K40 is free, as shown, while the leg K41 is positioned in a short slot K42 in the lever K20. The central portion K38 of the key K1, is stamped with three inverted U-shaped slots K43 therein, thus forming teeth K44. Into the upper portion of each slot K43, there extends a short finger K45 (Fig. 25). The fingers K45 are integral with the palm bars and are offset into the plane of the central portion K38 of key K1. The side portions of the slots K43 are of such a size as to allow the fingers K45 to pass on either side of the teeth K44, depending upon the position of the key K1, when the palm bars are depressed. Thus, unless the key K1 is in either its extreme right-hand (operated) position or is in its extreme left-hand (normal) position, the teeth K44, thereof, will block depression of any of the palm bars. Also, it is to be understood that if any palm bar is depressed, its finger K45 will block movement of the key K1. Thus a simple and efficient interlock is provided between the palm bars and the accumulator shift key K1.

The key K1 is limited in its motion in either direction by the finger K45. When the key K1 is moved to its right-hand position, its lower left leg K41 moves such a distance that it picks up the lever K20 and moves the lever (and consequently the whole shaft K18) a distance equal to the thickness of two actuating plates. Hence, it moves the lifting-arm K21 from alignment with the add plate AP3 into alignment with the grand-add plate AP5. Also the lifting-arm K22 is moved from its alignment with the subtract plate AP4 into alignment with the grand-subtract plate AP6. Further, the lower right leg K40, of the key K1, contacts the lever K23 and moves its lifting-arm K24 into alignment with the grand-total plate AP11 regardless of which of its four lateral positions the lever K23 may have assumed. In regard to the lever K23, the slot K27 is long enough so that, when the lever K20 is moved toward the right of the machine, by the movement of K1, the total-selecting lever K6 will not be moved regardless of which position it assumes. After the key K1 is released, the shaft K18 is returned to the left-hand side of the machine by the spring K35 and the lever K23 is returned, by spring K37 to its previous position which position is determined by the setting of the total-selecting lever K6.

From the foregoing, it is seen that when the accumulator-shift key K1 is held operated, then depression of the palm bars K2, K3, or K5 will respectively lift the tails of the actuating-plates AP5, AP6, or AP11.

The correction key K4 is best shown in Figs.

24 and 43. The downwardly extending stem of this key is bent at right angles at K47 (Fig. 43) toward the rear of the machine and is, at its bottom, bent toward the right-hand side of the machine and then bent upward to form a toe K48. Thus, when the correction key is operated (by pressing its top toward the front of the machine) it pivots about its rivet F47 (Fig. 44) and raises the toe K48 (Fig. 43) to lift the tail of the correction actuating-plate AP2, but, due to its shape, it does not move the plate AP1. Fig. 43 shows the key in fully operated position.

Means are provided, in the present machine, for preventing the lifting of more than one actuating plate tail at a time or during a cycle of operation and also an inter-locking mechanism is provided between the palm bars, the digit keys and the actuating-plates and these means are best shown in Figs. 20, 63, 64, and 65. Referring particularly to Fig. 63 it is seen that the tails of all the actuating-plates (except the multiply plate AP1) are beveled along their left-hand upper edges. Suspended above the beveled tails, and loosely mounted upon the vertical cross-brace F34 is a series of pendants AP13. The right-most pendant AP14 (Fig. 63) is merely a spacing member. The left-most pendant AP13 (Fig. 63) has attached thereto, by a short screw AP15, a flat leaf-spring AP16. This spring tends, constantly, to press the pendants against the right-hand wall of the bail-shaped actuating-plate frame F22 and thus tends to keep the pendants in proper vertical alignment with the actuating-plates. When the plate AP1 is raised, its tail portion passes into the space between the left-hand vertical portion of the frame wall F22 and the left-most pendant AP13. Thus, no other actuating-plate can be lifted until AP1 drops to its unoperated position. From the foregoing, it is seen that, when any one of the plates AP2—AP11 is raised, its beveled tail will separate the pendants and thus prevent any other plate from being raised. It is obvious that any well known type of pendant lock may be substituted at this point. Referring particularly to Fig. 64, a forwardly extending rocking ball AP18 is pivoted upon the shouldered screw F33 (see also Fig. 20). A spring AP19, coiled about the screw F33, anchored at one end to the left-hand bail-arm AP20 and at its other end to the left-hand vertical portion of the frame F22, tends constantly to hold the ball AP18 against the tails of the actuating-plates and yieldingly hold the actuating plates down. The right-hand arm AP21 (Fig. 64) of the ball AP18, is formed so that it extends upward and has, at its top a cam-edge AP22 (see Fig. 18). As is best seen in Figs. 18, 64, and 65, a cross-brace F50, which brace is a part of the cam-carriage framing to be later described in detail, has slidably mounted thereon, by means of shouldered screws F51 and slots F52 (Figs. 64) a pair of ball-lock-actuating slides AP23 and AP24. Each slide has, at its upper end, a rearwardly bent finger AP25 which finger is for engagement with the balls of the digit-key ball-lock F14 previously described. The foremost slide AP24 is activated only during multiplication and it will, therefore, not be described at this time. The slide AP23 is so positioned that its right-hand lower corner rests upon the cam surface AP22 of the right-hand ball arm AP21. When any of the plates AP2 to AP11 (inclusive) are raised, the ball AP18 is swung clockwise (Fig. 18) and the cam edge AP22 acts upon the slide AP23 and raises it so that its rearwardly projecting finger AP25 enters between the balls of the ball-

lock and spreads the balls so that no digit key can be depressed.

ACCUMULATOR ENGAGING AND DISENGAGING

The means for engaging and disengaging the accumulators is best shown in Figs. 18, 20, 21, 26, 28-37, inclusive, 45 and 46. With particular reference to Figs. 45 and 46, it is seen that, mounted upon the right-hand ends of each of the accumulator shafts A22, is a bail A76 having a left-hand forwardly-extending arm A75, and an upwardly-extending right-hand arm A77. At their right-hand sides the bails A76 are pivoted upon shouldered screws A78 (see Fig. 18) which screws are made fast in the upright rear portion F26 of the actuating-plate frame F22. Thus, it is seen (Fig. 12) that the bails A76 lie between the right-hand portion of the accumulator frame A15 (Fig. 45) and the actuating-plate frame wall F26 (Fig. 18). Pivotedly mounted, directly beneath the cross-portions of bails A76 are bails A79 (Fig. 45). These bails are mounted in holes A80 in the frame A15 (Fig. 45) and holes A81 (Fig. 18) in the frame-portion F26, the parts A82 and A83 (Fig. 46), respectively, extending into the holes A80 and A81. Toggle-springs A84 (Fig. 45) are anchored at their lower ends, in holes in the arms A77 of bails A76 and are anchored, at their upper ends, in holes A85 (Fig. 18) in the frame portion F26 of frame F22. As is seen in Figs. 45 and 46, the bails A79 are, at their right-hand ends, bent to form lugs A86 which lugs underlie the bail-arms A76. The actuating plates AP1 to AP11 lie in vertical alignment with the above mentioned bails and are individually shaped to operate the bails for throwing the accumulators into and out of mesh with their actuating racks at various times (during machine cycles) which times vary with the various kinds of machine cycles. For example, Fig. 45 shows the total-actuating plate AP10 in its position of rest. When its tail is raised no part of the plate will contact the bails A76 or A79 but, in the initial part of its forward stroke, a lug AP30 thereon, contacts the cross-portion of the bail A79 (upper accumulator) and swings the bail counter-clockwise. In so doing, the lug A86 contacts the arm A77 of bail A76 and swings the bail A76 clockwise far enough to move the toggle-spring A84 past center and the toggle-spring A84 then acts to swing the bail A76 to the full extent of its movement, thus meshing the accumulator wheels with the actuating racks. Near the end of the forward stroke, a cam edge AP31 contacts the top of the cross-portion of bail A76 and cams the accumulator out of mesh, it being understood that the bail A79 will cause no interference at this time as it swings back to its normal position as soon as the lug AP30 passes during the first part of the forward stroke. On the return stroke, the lug AP30 contacts the bail A79 and swings it clockwise without affecting the bail A76. During the machine cycle just described, the bails A76 and A79, associated with the lower accumulator, remain unmoved due to the design of the plate AP10.

From the foregoing, it is seen, generally, how the actuating-plates act to engage and disengage the accumulators, and the individual shapes of the plates (insofar as this function is concerned) will now be described in detail. Referring to Fig. 26, the multiplication plate AP1 is designed to engage and disengage the upper accumulator for repeated addition. Thus at the end of the forward stroke of the plate AP1, a

raised portion AP32, thereon, contacts the bail A79 (Fig. 45) and throws the accumulator into mesh. Near the end of the return stroke, a cam edge AP33 contacts the bail A76 and throws the accumulator out of mesh. The plate AP1 is blanked out in such a form that it does not move the lower accumulator.

The correction plate AP2 is shown in Fig. 28. This plate is so formed that its sliding front and rear motion will not engage or disengage either accumulator.

The addition plate AP3 is shown in Fig. 29. This plate is formed with a raised portion AP34 and a cam edge AP35. The raised portion AP34, when the plate is in motion, throws the upper accumulator into mesh at the end of the forward stroke and the cam edge AP35 throws the accumulator out near the end of the return stroke. The plate AP3 is so formed that it does not move the lower accumulator.

The plate AP4 is fully shown in Fig. 30. This is the subtraction actuating-plate and is so formed that it acts to engage and disengage the upper but not the lower accumulator. At the beginning of the forward stroke of this plate, a lug AP36 throws the accumulator into mesh and, near the end of the forward stroke, a cam surface AP37 throws the accumulator out of mesh.

The grand-addition actuating-plate AP5 is shown in Fig. 31. This plate is adapted to engage and disengage the lower accumulator but not the upper. By comparing Figs. 31 and 45, it is seen that a raised portion AP38 (Fig. 31) will, when AP5 is in motion, move the lower of the two bails A79 (Fig. 45) to throw the lower or grand-total accumulator into mesh at the end of the forward stroke and it is further seen that, near the end of the return stroke, a cam surface AP39 (Fig. 31) acts upon the lower of the two bails A76 to throw the lower accumulator out of mesh.

The grand-subtraction actuating-plate AP6 is shown in Fig. 32 and this plate is so formed as to engage and disengage the lower accumulator but not the upper. At the beginning of the forward stroke of AP6, a raised portion AP40 acts to throw the lower accumulator into mesh and, at the end of the forward stroke, a cam surface AP41 acts to throw it out of mesh.

The sub-total taking actuating-plate AP7 (Fig. 33) is so formed as to engage and disengage the upper accumulator but not the lower. At the beginning of the forward stroke, a lug AP42 acts to engage the upper accumulator and, near the end of the return stroke, a cam surface AP43 acts to disengage it.

The grand-sub-total taking actuating plate AP8 is shown in Fig. 34. This plate is designed to engage and disengage the lower accumulator but not the upper. At the beginning of the forward stroke, a raised portion or lug AP44 engages the lower accumulator and, near the end of the return stroke, a cam surface AP45 disengages it.

The transfer-total actuating-plate AP9 is shown in Fig. 35. This plate is designed to engage and disengage both the upper and lower accumulators. Thus, at the beginning of the forward stroke, a lug AP46 engages the upper accumulator with the actuating racks. At the end of the forward stroke a cam surface AP47 disengages the upper accumulator and a raised portion AP48 engages the lower accumulator. Near the end of the return stroke, a cam surface AP49 disengages the lower accumulator.

The total taking actuating-plate AP10 is fully shown in Fig. 36, but as this was described in

connection with Fig. 45 it will not be redescribed here.

The grand-total taking actuating-plate AP11 is shown in Fig. 37 and this plate is adapted to mesh and unmesh the lower, but not the upper, accumulator. At the beginning of the forward stroke, a lug AP50 engages the lower accumulator and, near the end of the return stroke, a cam surface AP51 disengages it.

From the foregoing it is seen how each actuating-plate is shaped to engage and disengage the accumulators and their actuating racks. Other significant actuating-plate shapes which are associated with sector-swinging, carriage return, etc. will be described in detail later under appropriate headings.

THE CARRIAGE AND CAMS

The present machine is equipped with a laterally movable cam carriage upon which numerical representations may be impressed by operation of the digit keys. After an amount is impressed or set up in the cam carriage, the cams are rotated and the cams, themselves, swing the type-sectors S (and consequently the rack segments S1) to turn the accumulator wheels. The carriage and cams or parts thereof are shown in Figs. 12, 14, 15, 20, 22, 48, 49, 52, 56, 57, 60, and 61. The framing in which the carriage is mounted is rather complex and is very important, in view of the fact that other major mechanisms are also mounted therein, and this framing will now be described. Referring particularly to Figs. 12, 49 and 52, it is seen that, directly behind the right-hand motor frame-wall F19 (Fig. 12), there is a large upright frame-wall F55 (see also Fig. 13). At the front of its top edge (Figs. 12 and 49) the wall F55 is formed and bent leftwardly into a lug F56. This lug is drilled and threaded to receive a screw and thus hold it to the main casting F1. Near the rear of its upper edge, the wall F55 is bent leftwardly to form a horizontal surface F57 from which are bent downwardly two ears F58 and F59 and it is upon these portions F57, F58, and F59 that many of the parts of the remultiply and constant-factor mechanisms are mounted. Directly opposite the upright frame-wall F55, on the left-hand side of the machine, is an upright frame-wall F60 (Figs. 12, 49 and 52, see also Fig. 14). At the front of its top edge, this frame-wall F60 is bent rightwardly into an elongated lug F61 (Figs. 12 and 49). This lug F61 is drilled and threaded so that it may be screwed to the main casting F1. The cross-brace F50 is mortised, at its right-hand end, in the upright frame wall F55 (Figs. 13 and 49) and is mortised, at its left-hand end, in the upright frame-wall F60 (Fig. 14). A front view of the cross-brace F50 is shown in Fig. 64. A second cross-brace F62 (Figs. 12, 49 and 52) is mortised, at its right-hand end, in the upright frame-wall F55 (Fig. 13) and is mortised, at its left-hand end, in the frame-wall F60 (Fig. 14). This completes the framing structure for the carriage unit. The assembled carriage frames may also be seen, unencumbered by any mechanism, in the bottom-plan view (Fig. 23).

The description of the carriage and its cams now follows: Referring particularly to Figs. 49, 52, 56 and 57, the main frame of the carriage itself is single-piece and bail-shaped. The frame has a horizontal cross-portion C1 (Fig. 49) which is bent into an upright C2 (Fig. 52). At its right-hand end, the carriage frame is bent downwardly into a side-plate C3 (Figs. 49, 52, and 56)

and, at its left-hand end, the carriage frame is bent downwardly into a similar side plate C4 (Figs. 49, 52, and 57). Near the right-hand end of the cross-portion C1, a lug C5 is formed (Figs. 52 and 56). The plate C3 (Fig. 56) is fastened, by four countersunk screws C6, to a ring C7 (see also Figs. 49 and 52) which ring forms a bearing for a rotatable disc C8 (Figs. 56 and 15). Referring to Fig. 57, it is seen that the left-hand side plate C4 is fast to a ring C9 which forms a bearing for a rotatable disc C10. The discs C8 and C10 are fastened by screws C11 (see Fig. 57) to the ends of a channel bar C12 (see also Figs. 20, 48 and 57) of inverted U-shaped cross-section. This channel bar C12 extends, inside the carriage, from the inside of the disc C8 to the inside of the disc C10 and is mounted, for sliding movement, upon a shaft C13 (of square cross-section) which shaft extends laterally across the machine as is shown in Figs. 49 and 52. The shaft C13 is fastened by two screws, at its left-hand end (see Fig. 14), to a small rocking-plate C14 in which is fast a shouldered screw C15 which passes through and forms a pivot for the rocking plate with the frame F60. The shaft C13 is mortised, at its right-hand end (see Fig. 15) in a small rocking-plate C16. The rocking-plate C16 (see Fig. 13) has, fast therein, a shouldered screw C17 which screw is journaled in the frame wall F55. The wall F55 is counter-bored (Fig. 49) to receive the head of the screw C17 and a washer C19 spaces the rocking plate C16 from the frame wall F55. Referring particularly to Figs. 48 and 49, the channel bar C12 (Fig. 48) is formed with slots C18 in which slots there rest a plurality of vertical walls or spacers C20 (see also Fig. 49). A bar C21 (Fig. 48), the same length as the channel bar C12, is slotted at C22 along its lower edge and the walls C20 also engage in these slots C22. A shim C23 is interposed between the channel C12 and the slotted bar C21 so as to hold the walls C20 firmly in place. Between the walls C20 are positioned cams C24. In the present instance, there are thirteen cams C24 and fourteen walls C20. The wall C20, nearest the left-hand side of the machine is rigidly fastened to the bearing disc C10 (of Fig. 57) and the wall C20, nearest the right-hand side of the machine, is rigidly fastened in any suitable manner to the bearing disc C8 (of Figs. 15 and 56). Thus, when the carriage is assembled, the discs C8 and C10 are held in vertical alignment with their respective rings C7 and C9. Each wall C20 is drilled to receive the lower ends of a pair of coiled expansion springs C25. The opposite ends of springs C25, which ends are bent toward the right-hand side of the machine, are anchored in holes in the cams C24 (see Fig. 61). The springs tend constantly to hold the cams C24 in their uppermost or normal positions. Referring to Figs. 48 and 61, it is seen that the walls C20 are stamped out at C26 and are milled thin at C27, thus forming sprung portions C28. Each portion C28 is stamped and bent so as to form a downwardly extending tooth C29 and two leftwardly extending teeth C30 which teeth C30 are adapted to engage teeth C31 milled in a pair of uprights C32 which uprights are integral with the cams C24 and are so spaced from each other as to engage the sides of the channel bar C12 which bar guides the cams as they are depressed or released from their depressed positions. The downwardly extending teeth C29 of the walls C20 are positioned in slots C33 (Fig. 48) in a locking bar C34 which bar C34 extends through a slot in

the disc C10 (Fig. 57) and is bent upwardly as shown. The opposite end of the locking bar C34 rests in a slot C35 (Fig. 56) in the disc C8. The locking bar is slidably mounted in a groove (Fig. 48) in the channel bar C12. From Figs. 48 and 61, it is seen that, whenever a cam C24 is depressed, the teeth C31, thereof, will ratchet past the teeth C30 thus springing the portions C28 of the associated wall C20. This causes a vibratory movement of the tooth C29 (of the associated wall C20) but does not move the locking bar C34 due to the fact that the slots C33 are made wider than the thickness of the teeth C29. It is to be noted, at this point, that the cams C24 are made to accommodate the springs C25 as is particularly shown in Figs. 60 and 61. From these figures, it is seen that each cam is counterbored at CB, thus providing a space for the springs C25 when the cams are assembled. It is also seen that each cam C24 is slotted (on its left-hand side) at the top, as is indicated at CS. Thus, it is seen that the teeth C30 hold the cams C24 in their various depressed positions, against the tension of springs C25 and this is particularly well illustrated in Fig. 61. The locking bar C34, which is normally tensioned by the springy portions C28 in a normal locking position wherein the teeth C30 engage teeth C31, is used to lock the cams C24 in their depressed positions during rotation of the cams and is also used to release the cams from their depressed positions so that the springs C25 may return them to normal as will be described in detail later. At this point it is sufficient to say that whenever the locking slide C34 is moved toward the left-hand side of the machine (toward the right of Fig. 48) the slots C33 will press against the teeth C29, of walls C20, and will thus positively keep teeth C30 from becoming disengaged from the teeth C31 of the depressed cams C24. Also, if the locking slide C34 is moved in the opposite direction (or toward the right-hand side of the machine) the slots C33 will press against the teeth C29, of walls C20, and will spring teeth C29 and C30 to such an extent as to positively disengage teeth C30 from the teeth C31 of any depressed cams C24, thus allowing springs C25 to raise the depressed cams C24 to their uppermost positions. The entire carriage is slidably mounted upon the square shaft C13.

The square shaft C13 may be arcuately swung about its pivot points, i. e., screws C15 and C17 so as to rotate the cams C24 and walls C20, as a unit, within the rings C1 and C9 (Figs. 56 and 57) and the means for swinging the square shaft C13 will now be described. This means is best shown in Figs. 15, 49, 52, and 64. Referring to Figs. 15 and 52, it is seen that a slide C38 is made with a leftwardly bent arm C39 thereon. This arm C39 extends across the paths of all the actuating plates AP1 and AP11 as is shown in Fig. 52. The slide C38 (Fig. 15) is made with two slots C40 therein. The slide C38 is supported and guided, at its forward end, by means of a headed rivet C41 (Figs. 15, 64, and 65) which passes through the front slot C40 and is fastened in a rearwardly bent arm F65 which arm is integral with the cross-brace F50. The slide C38 is supported and guided, at its rear end, by means of a large-headed shouldered screw F66 (Fig. 52) which is fastened into the frame wall F55. A spacer F67 (Fig. 15, 49 and 52) separates the slide C38 from the frame wall F55. The slide is constantly urged toward the front of the machine by a spring C42 (Fig. 15) which is an-

chored, at its front end, to a pin C43 extending leftwardly from the frame wall F55 and anchored, at its rear end, to an upright lug C44, integral with the slide C38. The slide is formed with two teeth C45 thereon (Figs. 15 and 49) which teeth cooperate with three teeth C46 (integral with rocking plate C16) for arcuately swinging the square shaft C13. Thus it is seen that, whenever the slide C38 is moved rearward in the machine, the teeth C45 will engage the teeth C46 and rotate the cams of the cam carriage. There are two means for moving the slide C38, one of which is the actuating-plates and this means will now be described. Referring particularly to Fig. 20, it is seen that the actuating-plate AP3 is made with a notch AP53 in its upper edge. Identical notches AP53 are formed in the actuating plates AP1 (Fig. 26), AP4 (Fig. 30), AP5 (Fig. 31), AP6 (Fig. 32), AP7 (Fig. 33), AP8 (Fig. 34), and AP9 (Fig. 35). When the tail of any of these plates is raised, the notch AP53 (see particularly Fig. 20) engages the leftwardly bent arm C39 of the slide C38 (Fig. 15) and, hence, the slide C38 is positively driven rearward and forward by the actuating plate. It is to be noted that an element of time is introduced between the initial movement of slide C38 and the beginning of rotation of the cams C24. Further, another element of time is introduced between the end of rotation of cams C24 and the end of movement of slide C38. The reason for the above two time elements is to allow the proper meshing and unmeshing of the accumulators and also to allow proper timing in carriage return operations, etc. The timing elements are permitted by the construction and arrangement of the slide C38. From Fig. 15, it is seen that slide C38 moves a certain distance before teeth C45 contact teeth C46. Also, before slide C38 has completed its rearward movement, the teeth C45 leave teeth C46. The correction actuating-plate AP2 (Fig. 28) is formed with an elongated notch AP54, instead of a small notch such as AP53, and the elongated notch AP54 is so arranged in the plate AP2 that the plate may be driven rearward and forward without engaging the arm C39 of slide C38 and hence without rotating the cams C24 of the cam carriage. The actuating plates AP10 and AP11 (Figs. 36 and 37) are made with elongated notches AP55. These notches AP55 are arranged so that the slide C38 may be moved rearward in the machine by other means (to be described in detail in connection with the remultiplying mechanism). The reason for rotating the cams C24 is to move the type sectors S and their associated actuating racks S1 as was previously mentioned. This can best be understood from Fig. 48. Two cams C24 are there shown in their normal or uppermost positions. A rotation of the cams in this position would not affect the sectors S at all, but if a cam is first depressed and then rotated, it will move the sector S, with which it is aligned, a distance proportional to the amount the cam is depressed. This is due to the fact that the cam acts upon the main stem of the sector S and also upon the upright heel S2 thereof so that the sector is positively driven in both directions by the periphery of the cam. The cams when in their normal position (see Fig. 20) are rotated concentric to the pivot screws C15 and C17 for shaft C12 and thus no movement of sectors S occurs. It is to be understood that the cams C24 are made very slightly elliptical so as to allow a clearance between the cams

and the main stems of the sectors S and the heels S2, thereof, when the cams are in zero or normal position.

CAM DEPRESSION

The cams C24 are depressed by the sectors S at certain times (described in detail in connection with the remultiply mechanism) and are depressed also by the digit keys of the machine. The depressing of the cams C24 by the digit keys will now be described. Referring particularly to Fig. 48, it is seen that each cam C24 is formed with a hook C48 at its top which hook is adapted to be engaged by a depressor hook C49. Each digit key is made with a slot K50 therein which slot is adapted to engage and rock a universal bar K51 (see also Figs. 49 and 64). The slots K50 are cut at varied angles so that each digit key will, when depressed, rock the universal bar an amount which is proportional to the number marked on its key-cap. Thus, the "0" digit key is so slotted at K50 that it does not move the universal bar and the angle of the slot K50 in the "9" digit key is such that the universal bar K51 is rocked further than by any of the other keys. This principle is old and well known in the art. Referring particularly to Figs. 64 and 65, the universal bar K51 runs laterally across the machine. The bar K51 is riveted, at each end, to a shouldered hub K52. The left-hand hub K52 is journaled in a small offset arm K53 which arm is screwed to the left-hand frame wall F60. The right-hand hub K52 is journaled directly in the right-hand frame wall F55. A spring K54 (Fig. 64) is coiled about the right-hand hub K52 and one end of the spring is anchored against the rear face of the universal bar K51 while the opposite end of the spring is anchored on the front of a pin K55 which pin is fast in the wall F55. Thus the spring K54 tends constantly to hold the universal bar K51, in an upright position, against the pin K55. Referring to Figs. 48 and 64, the universal bar K51 is bent, along its lower edge to form a pair of forwardly extending ears K56 and a pair of depending lugs K57 (one ear and one lug being shown in Fig. 64). The ears K56 are riveted to a clutch plate K58 (see also Fig. 65) upon which the depressor hook C49 is mounted for forward and rearward sliding movement. Thus, the clutch plate K58 follows the rocking movements of the universal bar K51. The depending lugs K57 are riveted to flattened portions of a short stub-shaft K59 (see Fig. 64). This stub-shaft K59, along with the clutch plate K58, supports and guides the depressor hook C49 so that, at certain times during multiplication cycles the clutch plate K58 may be rocked without rocking the depressor hook. The depressor hook C49 is normally held as shown in Fig. 48 by means of a spring C50 (Fig. 65) which is anchored, at its forward end, to the depressor hook C49 and, at its rear end, to the clutch plate K58. From the foregoing, it is seen that rocking of the universal bar K51, with the depressor hook in the position shown in Fig. 48, results in rocking the clutch plate K58 without moving the hook C49 or depressing a cam. It will be noted, however, that by moving hook C49 bodily toward the front of the machine, a pair of notches C52, cut therein, will engage the plate K58 and the depressed hook will also be drawn into locking engagement with one or another of the hooks C48, on the cams C24. Subsequent rocking of the universal bar K51, by a digit key depression, will then positively swing the de-

pressor hook and depress a cam C24. It is also to be noted that, due to the above locking engagement of the depressor hook C49 and cam C24, the cam is prevented from being overthrown during key depression. Therefor, there is a means, provided in the present invention, for moving the depressor hook C49 from its normal or Fig. 48 position to its active or engaged position and this means will now be described (Figs. 22, 48, and 49). Referring to Fig. 48, a bell-crank C54 is made with a rightwardly extending arm C55 which is bent downwardly to form a finger C56. A rearwardly extending arm C57 has bent up, therefrom, a finger C58. This finger C58 (see Figs. 49 and 51) constantly engages an aperture in the cross bar F62 and is limited, in its movements, by the sides of the aperture. Normally, the finger C58 rests against the left-hand side of the aperture C59 formed in a shuttle rack C60 (Figs. 49 and 51) preferably of a single-piece die stamping. The rack is formed with ten lugs C61 thereon which lugs extend toward the front of the machine. A lug C61 underlies a beveled end K501 on each of the digit-key levers and is adapted to be engaged and moved, thereby, whenever a digit key is depressed. The shuttle rack C60 (see Fig. 51) is formed with a downwardly and leftwardly extending heel C62 thereon and is slidably mounted upon the cross brace F62 by means of shouldered screws F69. From the foregoing, it is seen that whenever the shuttle rack C60 moves rightwardly it moves the bell-crank C54 (Fig. 48) clockwise against the tension of an expansion spring C63. This spring is coiled about the head of a shouldered screw C64 which passes through the bell-crank C54 and threads into an ear F70 bent off from the cross brace F50. From the foregoing, it is seen (Fig. 22) that, upon depression of a digit key, the beveled portion K501 of the key lever, cams the shuttle rack C60 toward the right-hand side of the machine, thus moving bell-crank C54 so that finger C56 thereon engages the surface C66 on the depressor hook C49 and moves the hook into engagement with the cams C24 and the clutch plate K58, during the first part of the down stroke of the digit key. At this time the slot K50, in the key-lever, engages the universal bar K51 and continued downward travel of the key lever rocks the bar K51 which in turn rocks clutch plate K58 and hook C49 thereby depressing a cam. When the key lever reaches the bottom of its downward stroke, its beveled end passes beneath the lug C61 on the shuttle rack C60 and the rack is released so that it returns to its normal position under tension of spring C63. As the shuttle rack moves to normal, the bell-crank C54 follows and allows the depressor hook (under tension of spring C50, Fig. 49) to disengage itself from the clutch plate K58 and the cam C24. On the up stroke of the key lever, the beveled portion K501 of the lever engages the lug C61 on shuttle rack C60 and moves the rack from its normal position toward the left-hand side of the machine. This leftward movement of the shuttle rack causes the cam carriage to step to the left and position a new cam under the depressor hook.

CARRIAGE ESCAPEMENT

Referring to Fig. 49, the machine is equipped with a horizontally disposed escapement rack C70. This rack C70 is formed with a lug C71 (dotted) on its left-hand end which lug is journaled in a V-shaped slot C72 (see Fig. 14) cut

in the frame wall F60. On the right-hand end of rack C70, a similar lug C73 extends into another and similar V-shaped slot C74 (Fig. 18) in the downwardly bent ear F58 of the frame wall F55. These slots are of such a size as to allow the escapement rack to pivot, therein to four different positions E1 to E4, inclusive. These positions are indicated, in dotted lines, in Fig. 56. During normal carriage escapement, the rack C70 oscillates between the central positions E2 and E3 in which positions the rack C70 engages one or the other of pair of escapement dogs C75 and C76 on the upright portion C2 of the carriage frame. The dogs C75 and C76 are well shown in Figs. 49, 52, 56, 58, and 59. Referring particularly to Figs. 58 and 59, it is seen that the portion C2 of the carriage frame is slotted at C71. At the right-hand end of the slot C71 (left-hand end as seen in Figs. 58 and 59) there are formed two cutouts C78 and C79. In these cutouts are slidably mounted a pair of oppositely disposed ears C80 of the stepping dog C75. A retaining plate C81, screwed to the frame-portion C2, holds the stepping dog C75 in the slot C71. The ears C80 of the dog C75 also act as trunnions so that, if the escapement rack is in its E2 or normal position and the carriage is pulled toward the right-hand side of the machine, the stepping dog C75 may ratchet past the teeth of the escapement rack. A spring C82 tends constantly to draw the stepping dog into the teeth of the escapement rack C70. The spring is anchored, at one end, in a notch in the dog C75 and is anchored, at its other end in a hole in a lug C83 in the retaining plate C81. The permanent dog C76 is integral with the frame portion C2. Normally the stepping dog is in engagement with the teeth of the escapement rack C70 as is shown in Fig. 56. When the rack C70 is raised to the E3 position, the permanent dog C76 engages it and the dog C75 (under tension of spring C82) steps one tooth space toward the left-hand side of the machine. The dog C75 is limited in its movement by the cutouts C78 and C79. When the escapement rack C70 returns from its E3 position to its E2 position, it disengages the permanent dog C76 and engages the stepping dog C75. The carriage then steps one step or tooth space toward the left of the machine while the stepping dog remains stationary thus stretching the spring C82. The carriage is constantly urged toward the left-hand side of the machine by a spring-tensioning device which will now be described. Referring particularly to Figs. 49 and 52, the retaining plate C81 for the dog C75 is formed with a pair of ears C84 and C85. The ear C84 holds one end of a cord C86, the opposite end of which is fast to a pulley C87 which pulley is journaled in the cross-frame F62 in the following manner: Referring to Figs. 49 and 51, the pulley C87 is made with a shank C88 (Fig. 51) which extends through a large hub C89, the hub C89 being shouldered and riveted to the cross-brace F62. A thin washer C90 (Fig. 49) fits flush against the end of the pulley shank C88 which shank extends forward just slightly farther than the hub C89. A screw C91 threads into the shank C88 thus holding the washer C90 tightly against the shank C88 and allowing the shank C88 to turn freely in hub C89. A coiled contractile spring C92 is coiled about the hub C89 and is fastened to the washer C90 and the cross-brace F62. Thus the spring C92 tends constantly to wind up the pulley C87 and thus draw the carriage toward the left-hand side of

the machine. As the carriage steps toward the left-hand side of the machine, the tension on the spring C92 becomes lessened.

The means for moving the escapement rack C70 from its E2 position to its E3 position and back is as follows:

Referring to Fig. 50, a hub C94 is shouldered at both ends. The left end of the hub is riveted in the frame wall F60 as shown while the right end of the hub loosely holds a coiled spring C95. Adjacent the hub C94 is a collar C96 mounted upon the smooth shank of a screw C97 which, at its left end, threads into the hub C94. Adjacent the collar C96 is a rearwardly extending resilient arm C98 which extends through a slot C99 in the cross-brace F62 (see also Fig. 51). Thus, the screw C97 holds the arm C98 and the collar C96 and hub C94 tightly together. The spring C95 has a pair of rearwardly extending arms C100 which extend through cutout portions of the cross-brace F62 to engage and yieldingly hold the escapement rack C70 in its normal or E2 position. Thus, it is seen that, whenever the rack is moved from normal, one or the other of the spring arms C100 will tend to return it to its normal position. The leftwardly extending heel C62 of the shuttle rack C60 lies (in its normal position, as shown) tangent to the right-hand side of the resilient arm C98. At its rear end the arm C98 is formed into a leftwardly offset finger C101 which finger is positioned in a cut out portion of the escapement rack C70. Every time a digit key is depressed, the beveled end of the key lever cams the shuttle rack C60 leftward from normal, on the up stroke, as was previously explained. Thus, on the up stroke of a depressed key lever, the heel C62 of the shuttle rack C60 springs the arm C98 to the left and the finger C101 engages the escapement rack C70 and cams it up to the E3 position. When the key lever reaches its uppermost or normal position, the beveled end thereof passes above the associated lug C61 on the shuttle rack C60 and releases the rack. The resilient arm C98 then returns the shuttle rack to its normal position and, at the same time withdraws the finger C101 from engagement with the escapement rack. The escapement rack then drops to its normal position (E2, Fig. 56) under action of the spring C95.

CARRIAGE RETURN MECHANISM

The present machine is especially designed to handle decimals. With reference to Fig. 12, counting from left to right, there are thirteen type-sectors S, the first sector being the leftmost. An imaginary decimal point lies between the seventh and eighth sectors so that the seventh sector may be considered the "units" sector, the eighth may be considered the "tenths" sector, the ninth the "hundredths" sector, etc. Thus, the machine is conveniently arranged to compute "millions of a unit." In the present instance no means is shown for actually printing a decimal point as there are many ways of designating the position of the decimal point upon the printed tape. For example, the seventh or "units" sector S could carry type which could be made for printing a decimal point to the right of each numeral, or the type on the seventh and eighth sectors could be so positioned that, in printing, a slightly greater space would exist on the printed tape between the "units" and "tenths" columns than between the other columns.

The home position of the carriage, as is particularly shown in Fig. 12, is that position in which

the leftmost cam C24 is in alignment with the tenth or "thousandths" sector S. For this reason, the present machine is equipped with an automatic carriage return mechanism which will return the carriage, from either the left-hand or right-hand side of the machine, to its home position and this mechanism will now be described. With particular reference to Fig. 52, there is, riveted to the side wall F55, a large hub C105 (see also Fig. 13). This hub is made with a disk portion C106. The face of the disk C106 is drilled and threaded to receive the threaded end (not shown) of a similar hub which is formed with a disk portion C107. The hub, of which the portion C107 is an integral part, forms a pivot for four carriage-return arms C108, C109, C110, and C111 (see also Figs. 15, 49, and 71 A, B, C, and D). Referring to Figs. 49 and 52, a cord C112 is anchored, at one end, to the ear C85 on the escapement-pawl retaining-plate C81 and is anchored at its other end in a pulley C113. This pulley is pivotally mounted on a shouldered screw F100, as is shown in dotted lines in Fig. 52. The head of screw F100 is countersunk and the upper end, thereof, threads into the cross-portion F57 of frame F55. A smaller pulley C114, formed integral with pulley C113, has anchored therein the forward end of a cord C115. The rearward end of the cord C115 is anchored in a hole in the carriage-return arm C108. The normal position of the carriage-return arms is shown in Figs. 15, 49, and 71 A, B, C and D. Referring to Fig. 15, a pawl C118, for cooperation with two of the carriage-return arms, is pivoted upon a stub-shaft C119 (see also Fig. 52) which stub shaft is riveted or otherwise suitably fastened in the frame wall F55. The pawl C118 is slightly thicker than the carriage-return arms and is so positioned that it is laterally aligned with both of the carriage-return arms C110 and C111. Thus both the arms C110 and C111 cooperate with the pawl C118, as will presently be described. A spring C120 (Figs. 15 and 71B) is anchored, at its forward end, to the stub-shaft C119 and is anchored, at its rear end, in a hole in the carriage-return arm C109. The spring C120 constantly tends to urge the arm C109 clockwise. A spring C121 is anchored, at its upper end, in a hole in the carriage-return arm C110 and is anchored at its lower end, in a hole in the pawl C118. This spring C121 tends constantly to keep the nose of the pawl C118 in engagement with the carriage-return arms C110 and C111. Fig. 71C and D shows the carriage return arms and the pawl C118 in normal position and, in this position, the pawl is held against an arcuate surface C122 of the arm C110. The arm C110 is formed with a notch C123 in the periphery of its body portion and the arm C111 is likewise formed with a notch C124 in the periphery of its body portion. In the normal position of the carriage-return arms, the surface C122 on arm C110 holds the pawl C118 out of engagement with notch C124 in arm C111, (see Fig. 71D). The body portions (those portions enclosed by the hub-disks C106 and C107, Fig. 52) of all four carriage return arms are of the same diameter. Referring to Figs. 52 and 71A, the arm C108, which actually returns the carriage, is formed with a leftwardly bent lug C125 thereon. This lug extends far enough toward the left of the machine so that it lies in the path of travel of the arm C111 which arm operates the arm C108 to pull the cam carriage from the left-hand side of the machine to its home position. The arm C108 is made with another left-

wardly bent lug C126 which lug is formed on the periphery of the body portion of the arm C108. The lug C126 extends almost to the right-hand actuating-plate frame wall F22 and, during total cycles, lug C126 is engaged by mechanism (fully described under the heading Totaling mechanism) which acts upon the lug C126 to draw the carriage from any predetermined position to its extreme right-hand position. The lug C126 is not acted upon by any other carriage-return arm. The carriage-return arm C109 is formed with a small shoulder C127 (see Fig. 71B) at its upper end. Also, the arm C109 is formed with a small lug C128 (Figs. 71B and 49) which extends therefrom toward the left-hand side of the machine. This lug C128 lies in front of and in the plane of the arm C110, as is shown in Fig. 49. An expansion spring C129 (see particularly Fig. 52) is coiled about the disk 107 and is anchored, at one end, to the arm C110 and, at its other end to the arm C111. This spring tends constantly to press the arms C110 and C111 toward each other, that is, the spring C129 tends to press the arm C111 against the front side of a leftwardly bent lug C130 which lug is integral with the arm C110. The lug C130, as is shown in Figs. 14 and 52, extends through slots in the actuating-plates and is contacted and moved by any of the plates on the forward stroke during any kind of a machine cycle. Referring to Figs. 15 and 52, an expansion spring C132 is coiled about the disk C108 and is anchored, at its upper end, to the front of the arm C108 (Fig. 52) and at its lower end to the stub-shaft C119 (Fig. 15). This spring C132 is merely for the purpose of keeping a light tension upon the cord C112, attached to the upper end of arm C108. Referring to Figs. 15, 52, 54, and 56, it is seen that the two carriage-return arms C109 and C111 extend through a rockable latch plate C134. This latch plate is shown in detail in Fig. 54 where it is seen that the latch plate is formed with a bent up finger C135 on its left-hand side and, on the same side, is formed with a lug C136. When assembled in the machine, the lug C136 is journaled in a slot C137 of general V shape (see particularly Fig. 18) which slot is cut in the downwardly bent ear F58 of the frame wall F55. At its right-hand side (Fig. 54), the latch plate C134 is riveted to a short, slotted pin C138. This pin (see Fig. 52) is journaled directly in the frame wall F55. As is best shown in Fig. 55, the latch plate C134 is slotted at C139. Riveted to the latch plate C134 and extending above slot C139 are a retaining plate C140 and a spring C141. The spring C141 is made with a pair of arms C142 which extend toward the front of the machine and press down upon a pair of carriage stops C143 and C144 which stops are pivotally mounted upon the retaining plate C140 as shown. The slot C139 (Fig. 55) keeps the stops C143 and C144 in alignment with each other and also allows the stops to pivot about the retaining plate C140. The latch plate C134 is capable of being rocked counter-clockwise from its normal position (see Fig. 56) to a position, during carriage-return, where the stops C143 and C144 lie directly in the path of the lug or tooth C5 on the cross-portion C1 of the carriage frame. Whenever the latch plate C134 is moved to this position the bent up finger C135, thereon, contacts the escapement rack C70 and moves it counter-clockwise from its E2 position (shown in Fig. 56) to its lowest or E1 position wherein the escapement rack C70 is free of the stepping dog C75. This movement

of the escapement rack C10 causes clearing of the cam carriage as will be explained in detail under the sub-heading "Clearing the cam carriage." Referring to Fig. 55, the stops C143 and C144 are so arranged in the slot C139 that stop C143 can swing counterclockwise but not clockwise from its Fig. 55 position and the stop C144 can swing clockwise but not counter-clockwise from its Fig. 55 position. Thus, when the cam carriage is returned from the left-hand side of the machine, the tooth or lug C5, thereon, cams the stop C143 counter-clockwise and comes to rest against the stop C144. As soon as this happens, the stop C143 springs back to its normal position and prevents the carriage from recoiling, it being understood that the lug C5 is of such a width as to fit between the stops C143 and C144 when the stops are in their normal or Fig. 55 position. From the foregoing, it is seen that when the carriage is returned from the right-hand side of the machine (as, at the end of a total cycle), the carriage lug C5 will cam the stop C144 clockwise from its normal position and will come to rest against the stop C143.

The means for rocking the latch plate C134 will now be described. Referring to Figs. 68 and 69, a short cross-shaft F75 is threaded at its left-hand end and is screwed into the downwardly bent ear F59 on frame F57. The right-hand end of the shaft F75 is supported in a hole in the frame wall F55. Pivoted mounted upon this cross-shaft and lying flush against the ear F59 is a slide C150 of peculiar shape. The exact shape of the slide C150 is best shown in the detail-isometric Fig. 76. The slide has a forwardly extending toe C151 which is for engagement with the escapement rack (during re-multiply operations) and is used to raise the escapement rack to its E4 or uppermost position, as is described in detail under the heading "Remultiply mechanism." The slide C150 has also a forwardly and upwardly extending toe C152 which is adapted to engage and rock the latch plate C134 to permit actuation of certain of the carriage return arms. The slide C150 is also formed with a rearwardly bent ear C153 which is supported and guided at its forward end by the framing ear F58 and which is adapted to be engaged and raised by a bail-shape rocking plate C154 (see Figs. 68, 69, and 77). The rocking plate C154 is pivoted upon a shouldered screw C155 which screw is threaded (at its mid-portion) into the ear F58. The right-hand part of screw C155 is of smaller diameter than the left-hand or shouldered part. The rocking plate C154 (Figs. 74 and 77) is formed of a single piece of metal as shown. A rightwardly bent ear C156, thereon, underlies the ear C153 of the slide C150 and also bears against frame F58 thus holding the plate C154 from lateral displacement (see Figs. 67 and 68). The rocking plate C154 is formed with a rearwardly bent flap C157 which flap is adapted to be engaged by noses AP60 (see particularly Figs. 20 and 75), there being one nose AP60 on each actuating-plate. A spring C158 tends constantly to hold the rocking plate C154 in its normal position, as shown in Fig. 74. The spring C158 is anchored at its lower end, in a hole in the rocking plate C154 and is anchored, at its upper end to a leftwardly extending pin C159 which pin is fast in the ear F58. The slide C150 (Fig. 76) remains in its rearmost position (as shown) during carriage-return operations, in adding or subtracting cycles and in this position the toe C151 is clear of the escapement rack C10 and the toe C152 under-

lies a projection C160 on the latch plate C134 (see also Fig. 69).

The operation of all the carriage return parts in an addition cycle, will now be described. Referring to Fig. 15, the leftward stepping of the cam carriage (while the digits of a number, to be added, are being set up on the digit keys) through the pull of cord C112, draws the carriage-return arm C108 counter-clockwise from its Fig. 15 position against the tension of its spring C132. After the desired number has been set up on the digit keyboard, the add palm-bar K3 is operated and this raises the tail of the actuating-plate AP3. Referring to Fig. 20, as the tail of the actuating-plate AP3 rises, the nose AP60 contacts the flap C157 of the rocking plate C154 and cams the plate C154 counter-clockwise. This movement of the plate C154 is idle. As the plate AP3 moves rearward, in the machine, the nose AP60 moves away from the rocking plate C154 and the rocking plate immediately resumes its normal position. The actuating-plate AP3, continuing its rearward movement (forward stroke), picks up the long lug C130, of the carriage-return arm C110, and thus rocks the arm C110 clockwise (as seen from the right-hand side of the machine) to such an extent that the pawl C118 (Fig. 71C) snaps into the notch C123. The point C122 of pawl C118, due to the tension of spring C121, then holds the arm C110 cocked thus adding great tension to the spring C129 (Fig. 52). The actuating plate AP3 (Fig. 20), on its return stroke, continues toward the front of the machine and, as it nears the end of its travel, the ear AP60 again contacts the flap C157 of the rocking plate C154 and cams it to the position shown in Fig. 75. The ear C156 thus contacts and raises the ear C153 (Fig. 75) of slide C150 which pivots the entire slide about the stub-shaft F75. This pivoting of the slide C150 causes its toe C152 to engage and raise the projection C160 thus swinging the latch plate C134. Referring to Figs. 52 and 56, the two carriage return arms C109 and C111 are held in a hole C162 in the latch plate C134. When the latch plate C134 is swung to its Fig. 75 position, the arm C111 is released and under the tension of spring C129 (Fig. 52) the arm C111 swings (about its pivot) toward the rear of the machine. In so doing, it strikes the lug C125 (Fig. 52) and thus carries the carriage-return arm C108 toward the rear of the machine which, in turn, returns the carriage to its home position. Just as the cam carriage reaches its home position, a cam surface C163 (Fig. 71D) on the arm C111, cams the pawl C118 out of the notch C123 in the body of arm C110 and allows the spring C121 to return both the arms C110 and C111 to their normal positions, (shown in Figs. 71C and D). In the meantime, the latch plate C134 has been held in its operated position by the shoulder C127 (Fig. 71B) on the arm C109, it being understood that each time the latch plate C134 is swung to its operated position, the spring C120 urges the arm C109 a short distance toward the rear of the machine so that the shoulder C127 engages the latch plate C134 and holds it in its operated position until the arm C110 returns from its cocked position to its normal position. It is to be further understood that the arm C109 never escapes from the hole C162 in the latch plate. As the spring C121 (Fig. 71C) returns the arms C110 and C111, the arm C110 contacts the struck-

out lug C128 (Figs. 71B and 49), in arm C109, and moves it slightly toward the front of the machine thus removing the shoulder C127 from its locking position under the latch plate C134. The latch plate C134 then rocks under tension of a spring C165 (see Fig. 56) anchored, at its upper end to the cross portion F57 of the frame F68 and, at its lower end, in a hole in the forward edge of the latch plate C134. The return rocking of the plate C134 to its normal position causes it to relatch the arms C109 and C111 and also allows the escapement rack C10 to return to its E2 position wherein it engages the stepping dog C15. After the stepping dog is engaged by the teeth of the rack C10, the carriage steps leftward one step relative to the dog and is then in its home position. In the position of the parts shown in Fig. 75, wherein the actuating plate AP3 has completed its return stroke, but has not dropped to normal the latch plate C134 rests in such a position that the finger C135 is active to clear the cam carriage which is cleared during the return to home position as will now be described in detail.

Clearing the cam carriage

Referring to Fig. 57, it is seen that a rocking plate C170 is pivoted upon a shouldered screw C171 which screw is fast in the end plate C4 of the carriage frame. Another shouldered screw C172 passes through a slot C173 in the rocking plate C170 and threads into the end plate C4. This screw C172 guides the rocking plate C170 in its movements and also helps to hold the plate flush against the carriage end plate C4. A screw C174, which passes through the end plate C4 and threads into the ring C8, has a coiled expansion spring C175 mounted in a groove in the head thereof. Both ends of spring C175 press against the rocking plate C170 and thus hold the plate yieldingly in its normal position, as shown in Fig. 57. The plate C170 (see also Fig. 49) is formed with a leftwardly bent off ear C176, which lies flush against the bottom of the escapement rack C10. Plate C170 is also formed with a leftwardly and downwardly bent ear C177. As is shown in Fig. 57, the rocking plate C170 is formed with a pair of beveled points C178 and C179. The rocking plate C170 is approximately twice as thick as the locking bar C34. Whenever the locking bar C34 is drawn leftwardly (or toward the eye as seen in Fig. 57), it locks all the cams C24 and, whenever the bar C34 is pressed toward the right-hand side of the machine, it releases or unlocks the cams C24 thus allowing any cam which has been depressed, to return, under tension of its associated spring, to its uppermost or normal position. The rocking plate C170 is used to operate the locking bar C34 to lock and release the cams C24 as follows: Assume that a three-digit amount has been set up in the cam carriage. Three cams C24 have thus been depressed. The machine is now cycled for addition and, on the forward stroke, the cams C24 and locking bar C34 are revolved 90° clockwise, as seen in Fig. 57, from zero position. The zero position of the cams C24 is that position of the cams, whether they are depressed or not, wherein they have not been rotated. As the cams rotate, a point C180 on the bent-up portion of bar C34 strikes the beveled point C178 and the bevel then cams the bar C34 toward the left-hand side of the machine (or toward

the eye as seen in Fig. 57), thus locking all the cams C24. The cams and locking bar are returned to their zero position on the return stroke of the cycle. Shortly before the end of the return stroke, the point C180 is released from the beveled point C178 and the locking bar C34 returns to its normal position. At this time, the carriage-return mechanism takes effect and the escapement rack C10 is swung down to its E1 position simultaneously with the rightward (or return) movement of the carriage. The lowering of the escapement rack C10 to its E1 position causes the teeth of the rack to press down the ear C176 of the rocking plate C170 or to the position indicated in dot-dash lines in Fig. 57. Thus, the beveled point C178 is pressed against a surface C181 of the locking bar C34 and the bar is cammed toward the right-hand side of the machine or away from the eye in Fig. 57. This allows all the depressed cams C24 (three of them in the present instance) to return to their normal positions. Thus it is seen that the cam carriage is cleared while the carriage is returning to home position.

25

THE PRINTING SECTION

In the present machine, printing is accomplished by means of a plurality of spring tensioned hammers which, when released, strike 30 against the back-side of a paper and drive the paper against the type carried by the sectors S. A ribbon or other inking means may be positioned between the paper and the type-faces. Although there is no ribbon mechanism shown, in the present instance, it is obvious that many kinds could be used.

Referring to Fig. 11, the sectors S are positioned in cooperative relation to an anvil-block S4 so that when printing occurs, the anvil-block 40 backs up the sectors S and absorbs the shock of the printing hammers. The block S4 is slotted to receive the rack segments S1 which are integral with the type. The anvil-block S4 is fastened to the main casting F1 by means of screws 45 as shown.

Referring to Figs. 22, 23, and 27, the sectors S are pivotally mounted upon a cross-shaft F80 which shaft is fastened in opposite depending arms F81 and F82 of a bail shaped sector hanger which 50 is designated, generally, herein by the reference character F83. When assembled in the machine, the hanger F83 is made fast to the main casting F1 by means of screws which pass through holes in the casting F1 and thread into the hanger F83. The sectors S are spaced apart from each other by washers S9 (Fig. 23) and are spaced from the hanger-arm F82 by a washer S10. Referring to 55 Figs. 22 and 27, the hanger-arm F81 has, at its bottom, a lug F84 which is offset toward the left-hand side of the machine. Normally resting on top of the lug F84 is a small arm S12 which arm is made fast to the leftmost end of a rock shaft S13. The rock shaft is journaled in the hanger arms F81 and F82. A spring S14 is coiled around 60 the shaft S13 and one end of the spring S14 is anchored to the arm S12, while the opposite end of the spring is anchored under the lug F84. Thus the spring S14 tends constantly to hold the arm S12 against the lug F84 and to hold the rock shaft S13 against movement. As is best shown in Figs. 22 and 22A, the shaft S13 has, riveted to its midportion, a single piece spring S15 having a plurality of spring-fingers S16, there being one finger for each sector S. Each finger S16 engages 65 and is loosely held between a pair of lugs S17

75

which lugs are rightwardly struck out of the sectors S. Thus, during cycles of addition and subtraction, the cams C24 move the sectors S against the tension of the spring fingers S18. The means for swinging the sectors during totaling operations will be described under the heading Totaling mechanism. Each sector S is formed with a toe S18 which, in the normal position of the sectors, rests upon the cross portion of a U-shaped bracket F85. This bracket F85 (see Figs. 14 and 23) is made with a pair of bent-off ears F86 which ears are fastened by screws to small bosses F18, the bosses being integral with the main casting F1. It will be seen from Fig. 14 that the U-shaped bracket F85 is formed to receive and journal a cross-shaft P1 (see also Fig. 62). Referring particularly to Figs. 22 and 62, the left-hand end of cross-shaft P1 extends beyond bracket F85 and has, riveted thereto, an angle-piece P2 which piece has, integral therewith, an upright ear P3. The ear P3 normally engages the surface of the cylindrical portion of the main casting F1 (Fig. 22) and thus limits the rotation of the shaft P1 in a clockwise direction, as viewed from the right-hand side of the machine. Loosely mounted upon shaft P1 are nine hammer-release levers P4. These levers P4 are kept in alignment with the nine leftmost sector-toes S18 and normally, and is best shown in Fig. 22, the sector-toes S18 engage forwardly projecting fingers P5, of the levers P4, and thus hold the levers P4 in the position shown. The levers P4 (Fig. 62) are held in alignment with the sector-toes by means of washers P6 and a collar P7 which collar is pinned to shaft P1. Each lever P4 is formed with a notch P8 (Fig. 22) therein and a point P9 thereon at its upper rear end. A rocking frame frame P10 (Figs. 22 and 62) is formed with a pair of upwardly extending arms P11. A cross portion P12, thereof, is formed with two forwardly bent ears P13, thereon, which ears are pivoted upon the shouldered ends of smooth-shanked screws P14. The screws P14 are formed with threads near the heads and screwed into bosses F88 (Figs. 62 and 23). Thus the rocking frame P10 is held against lateral motion, in the machine, and is freely pivoted upon the screws P14. A spring P15 (Fig. 22), coiled about the left-hand screw P14, is anchored, at one end, against the cylindrical portion of the main casting F1 and is anchored, at its other end, to the rocking frame P10. This spring tends constantly to urge the rocking frame P10 counterclockwise (as seen in Fig. 22). As is shown in Figs. 14, 22, and 62, on the left-hand side of the rocking frame P10 and integral therewith, there is a long forwardly extending arm P16 the end of which engages the angle piece P2. Riveted to the upwardly extending arms P11, of the rocking frame P10, is a cross bar P17 upon which are pivotally mounted nine rock-plates P18. Each rock-plate P18 is formed with a rightwardly bent lug P19 and a depending lug P20 thereon. Each lug P19 is bent over into the plane of the lug P20 of the adjacent rock-plate P18. A spring P21 is stamped with a plurality of spring-fingers P22 therein. The fingers P22 each engage a lug P19 and thus tension the rock-plates P18 counterclockwise as viewed from the right-hand side of the machine. Also, the spring fingers P22 keep the rock-plates P18 properly spaced upon the bar P17. Referring to Fig. 22, each rock-plate P18 is formed with two rearwardly extending ears P23 and P24. The ears P23 normally contact the downwardly bent rear ends P25 of hammers P26,

as shown. Each hammer P26 is formed with a striking-face P27 and a spring-retaining hook P28. Referring to Figs. 12 and 22, the hammers P26 are mounted for sliding movement in a frame which consists of a pair of end blocks F89 and four-comb bars F90. The end blocks F89 conform to the cylindrical shape of the main casting F1 and are fastened thereto by screws F91 (Fig. 12). The two lower comb-bars F90 are mortised or otherwise suitably fastened into the end blocks F89 and the two upper comb-bars F90 are removably fastened to the end blocks F89 by screws F92. The comb bars F90 space and guide the hammers P26. For each hammer P26, there is a driving spring P29, which is anchored, at its forward end, to comb bar F90 and, at its rear end to the hook P28 of a hammer P26. The springs P29 are, in their normal positions, not tensioned. A recoil spring P30 is anchored, at either end to the ribs F2 of the main casting F1 and the central portion of the spring normally lies flush against the front portions of the hammers P26 and above the striking-faces P27. Thus, the hammers P26 are held in their normal positions by the recoil spring P30 and the driving-springs P29. In the present machine (see Fig. 12) the hammers, associated with the four rightmost sectors S have been left off so that the machine will print only two places to the right of the decimal point line. This arrangement, however, is optional and it is obvious that the machine could be made to print six places to the right of the decimal point line, if desired. Referring to Figs. 15, 16, 17, and 62, there is, loosely mounted upon the right-hand end of shaft P1, a U-shaped rock-lever P32 which is formed with arms P33 and P34. The arm P33 is made with a lug P35 upon its left-hand side. The lug P35 spaces the rock-lever P32 from the frame F85. A pair of rivets P36 hold the rock-lever P32 on the shaft P1. A spring P37, anchored at one end under the lug P35 (Fig. 16) and anchored, at its other end, under the right-hand ear F86 (Fig. 16) of the frame F85, is coiled about the shaft P1 and tends constantly to urge the rock-lever P32 clockwise as seen from the right-hand side of the machine. The normal position of the rock lever P32 is shown in Fig. 15. Referring to Figs. 16, 17, and 62, it is seen that the right-hand end of the shaft P1 is milled flat on opposite sides. Mounted for rocking movement, upon the flattened portion of shaft P1, is a clutch-pawl P40 of general U-shape. The clutch-pawl P40 (see Fig. 62A) is made with a pair of leftwardly extending lugs P41 thereon which lugs normally engage the outsides of the arms P33 and P34 (Fig. 62) of the rock-lever P32. It will be noted that the lower or rear lug P41 is shorter than the forward lug P41. A pin P42 (Figs. 16 and 17) fast in the shaft P1 holds the pawl P40 thereon. A spring P43, anchored at one end under the shaft P1 and anchored, at its other end, to the clutch-pawl P40 is coiled about the upper end of the pin P42 and tends constantly to keep the pawl P40 engaged with the rock-lever P32. Pin P42 is fast in shaft P1 and it is thus seen that the pawl P40 pivots upon pin P42. The upper leg of the clutch pawl P40 is notched at P44 (Figs. 16 and 62A) for engagement with the downwardly extending toe K62 of the printing-control lever or key K13. Referring particularly to Fig. 15, the printing-control lever lever K13 is pivoted upon a shouldered screw F93 which screw is fast in the upright portion 70 F26 of the actuating-plate frame F22. A washer

F94 spaces the lever K13 from the frame wall F26. The lever K13 is slotted at K63 so that at certain times, the lever may be lifted to an inactive position. The lever K13 is notched at K64 and, at its upper end, passes through a slot F95 in the main casting F1. Gravity holds the lever in its normal position, shown in Fig. 15, and in this position the lever permits printing during addition, subtraction and totaling cycles and prevents printing during "remultiply" cycles. If it is desired that the machine shall not print during an addition, subtraction or totaling cycle, then the lever K13 is moved to the front end of slot F95 and is held there. The lever is thus pivoted counter-clockwise about the screw F93 and its toe K62 (Fig. 16) acts upon the right-hand portion of the notch P44, in the clutch-pawl P40 and cams the pawl counter-clockwise about pin P42, so that the rear lugs P41 no longer engage the wall P34 of the rock-lever P32. In this disengaged position of the clutch-pawl P40, no printing can be accomplished by the machine as will now be explained. The actuating-plates, as shown in Figs. 20 and 62 are laterally aligned with the rock-lever P32 and each actuating-plate, except the multiply plate AP1 and the correction plate AP2, is formed with two printing-teeth AP62 and AP63 thereon. As an actuating plate moves rearward in the machine, the teeth AP63 and AP62, thereon, engage the rock-lever P32 and turn it counter-clockwise (Fig. 20) approximately 90° against the tension of its spring P37. If the clutch-pawl P40 (Fig. 62) is engaged, then the pawl, and consequently the shaft P1, will be swung with the rock-lever P32. The swinging of shaft P1 causes the angle-piece P2 to raise the arm P16, of the rocking frame P10 and thus swing the frame clockwise, as seen in Fig. 22. The rocking of the frame P10 cocks all the hammers P26, due to the engagement of the ears P23, of the rock-plates P18, with the rear ends P25 of the hammers P26.

Previous to this, the toes S18 of those sectors S, which have been swung by depressed cams C24, have moved away from their associated hammer-release levers P4 and thus certain of the levers P4 have swung (by gravity) clockwise until their rear ends rest against the cover of the machine. At the end of the forward stroke of the actuating-plate, the sectors S have been properly positioned at the printing line, (it being understood that, in the normal position of the sectors, the "0" type is positioned at the printing line), the hammers P26 are fully cocked, certain of the hammer-release levers P4 are in their normal positions and certain of the hammer-release levers P4 are in their operated positions. At this point, it is to be understood that the full cocking and the firing of the hammers P26 occur simultaneously at the end of the forward actuating-plate stroke. Those hammers P26, associated with the hammer-release levers P4 which are in their normal positions at the end of the forward stroke, are not released or fired by the levers P4, due to the fact that the points P9 of the levers P4 fit into the spaces P46 between the ears P23 and P24 of the rock-plates P18 and thus do not swing the rock-plates even though the hammers have been fully cocked. Those hammers P26, however, associated with the hammer-release levers P4 which have swung to their operated positions, are released or fired at the end of the forward stroke as follows: During the clockwise swinging of the frame P10 and just previous to the end of this swinging move-

ment, the ears P24, of the rock-plates P18, contact the points P9 of the operated release levers P4. By the time the clockwise swinging movement of frame P10 is complete, the points P9 have swung the rock-plates P18, clockwise about the cross-bar P17, far enough so that the ears P23 are pulled out of engagement with the rear ends P25 of the hammers P26. When this occurs, the hammers fire, under tension of their springs P29 and they strike first the recoil spring P30 and then the rear face of the paper or tape, thus driving the paper against the type-faces. The recoil wire P30 then returns the fired hammers to their normal positions.

- 15 It is to be understood that on the return stroke of every printing cycle, the tooth AP63 (see Fig. 20) positively engages and returns the rocking-plate P32 to its normal position thus permitting the spring P15 (Fig. 22) to return the frame P10 to its normal position. In returning, the ears P23, of those rock-plates P18 whose associated hammers have been fired, contact the rear ends of their hammers and are thus cammed clockwise so that the rock-plates pass under the rear ends of the hammers. The spring-fingers of the flat spring P21 then act to reposition the rock-plates P18 to their normal Fig. 22 position.

Means are provided for printing ciphers to the right of the lowest significant digit and these

- 30 means will now be described. Referring to Figs. 22 and 62, the rightwardly bent lug P19, of each rock-plate P18, lies partially in the plane of the depending lug P20 of the next rock-plate P18. Thus when any one of the rock-plates P18 is 35 swung, to release its hammer P26, the lug P19 thereon contacts the lug P20 on the next rock-plate and swings this rock-plate with the first. Thus, if the "1" digit-key were struck and the add palm bar were then depressed, the machine 40 would print 1. But, if the "1" digit-key were struck and then the "0" digit key were struck three times, subsequent cycling of the machine by the add palm bar would move only one sector S but the machine would print 10.00.

45

BACK-SPACING THE CARRIAGE

Means are provided for back-spacing the cam carriage and, in the present instance these means 50 include a manually operable back-space key K9. Referring particularly to Figs. 20, 52, and 53, the key K9 is preferably formed with an upright finger piece, thereon, and has a notch K68 (Fig. 52) in its right-hand end in which is anchored one 55 end of a spring K67. The opposite end of the spring K67 is anchored to the left-hand end of a housing K68. The spring K67 constantly tends to urge the key K9 towards the left-hand side of the machine. The housing K68 is made of a single piece of metal and is bent, as shown, so that a pair of lugs K69 extend, therefrom, toward the rear of the machine. The lugs K69 extend through slots K70 in the key K9 (see Fig. 52). The upper right-hand portion of the housing K68 60 is slotted to receive the finger piece of the key. The lower portion of the back-space key passes through a slot K71 (Fig. 52) in the keyboard plate F8 and the slot K71 limits the sliding motion thereof. The key is held upright and is 65 guided by the slot K71 and by the slot in the upper part of the key-housing K68. Referring to Fig. 52, it is seen that a rack BS1, having slots BS2, therein, is slidably mounted upon large-headed shouldered screws BS3 which screws pass 70 through the slots BS2 and thread into the rear 75

face of the cross-brace F62. Two springs BS4 are anchored, at one end in holes in the rack BS1 and are anchored, at their other ends, to screws BS5 which screws are fast in the cross-brace F62. The arrangement of the springs BS4 is such that they tend constantly to hold the rack BS1 up and toward the left-hand side of the machine as shown. Integral with the portion C2 of the carriage frame is an upwardly pointing tooth C183 and this tooth lies directly under the teeth of the rack BS1. To back-space the carriage, the key K9 is moved toward the right-hand side of the machine. Due to the shape of the slots K10, in the key K9, the initial part of the rightward sliding movement thereof forces the key and the rack BS1 down so that one of the teeth of the rack BS1 engages the tooth C183 on the cam carriage. Continued rightward movement of the back-space key causes the key to pick up a lug BS6, integral with rack BS1, and to move the rack BS1 and the cam carriage one space toward the right-hand side of the machine. This causes the stepping dog C75 to ratchet past a tooth on the escapement rack C70 and hence, when the back-space key is released, the carriage stays in its back-spaced position. It is to be noted, here, that the back-space mechanism is so arranged that the carriage cannot be overthrown during back-spacing.

ADDITION AND SUBTRACTION

Assume that the machine is clear and that it is desired to add the amount 37.5862 into the upper accumulator. The operator first depresses the "3" digit key. Referring particularly to Fig. 20 during the initial part of the down-stroke, the key enters the ball-lock F14 and spreads the balls apart so that no other digit key can be depressed. Also, the beveled end of the key, cams the shuttle rack C60 toward the right-hand side of the machine which causes the bell-crank C54 to cause the clutching of the depressor hook C49 and the clutch-plate K58 and also causes the point of the depressor hook C49 to engage the hooked portion C48 of the leftmost or first cam C24. It will be remembered that in the home position the first cam C24 is aligned with the tenth sector S. Continued depression of the "3" digit key causes its slot K50 to engage and swing the universal bar K51 which swings the depressor hook clockwise, as seen in Fig. 20, and thus depresses the cam C24 three tooth-spaces. As the "3" key reaches the bottom of its down-stroke, the beveled point thereof passes below the lug C61 on the shuttle rack C60 and thus releases the rack which then returns, under tension of spring C63 (Fig. 49), to its normal position. This return movement of the shuttle rack C60 and bell-crank C54 allows the depressor hook C49 to move rearward under action of spring C50. This rearward movement disengages the depressor hook C49 from the clutch-plate K58 and from the hook C48 on the cam C24. At this time, the operator releases the "3" digit key and the key rises. During the initial part of its up-stroke, the beveled point K501 of the digit key again contacts its associated lug C61, on the shuttle rack C60, and cams the rack toward the left-hand side of the machine. This leftward movement of the shuttle rack C60 causes the escapement rack C70 to be swung clockwise from its Fig. 20 or E2 position to its E3 position thus releasing the stepping dog C75, which dog immediately moves one step

toward the left-hand side of the machine. The entire carriage, as soon as the stepping dog has been released, moves almost imperceptibly toward the left-hand side of the machine until the permanent dog C76 contacts the teeth of the escapement rack C70. The carriage remains thus until the digit key has finished its up-stroke. As soon as the "3" key has completed its up-stroke, the beveled end, thereof, releases the shuttle rack C60 which then springs back to its normal position allowing the escapement rack C70 to return, under spring tension to its E2 position. In so doing, the escapement rack releases the permanent dog C76 and engages the stepping dog C75. The carriage then moves approximately one step toward the left of the machine, thus positioning the second cam C24 under the depressor hook C49. The operator subsequently depresses the "7", "5", "8", "6", and "2" digit keys thus depressing the second cam C24 (counting from left to right in the machine) a distance of seven tooth spaces, the third cam C24 a distance of five tooth spaces, etc. As each digit key rises, the carriage moves leftward one step so that, after the amount 375862 has been set up, the first cam C24 is aligned with the fourth sector S. If the addition palm bar K3 were now depressed, the machine would add 3758.620000 into the upper accumulator and would print 3758.62. Therefore, the operator operates the back-space key K9 twice, thereby positioning the first cam C24 in line with the sixth sector S, and then depresses the add palm bar K3. Depression of the palm bar K3 pivots the lever K20 counter-clockwise (Fig. 20) about the shaft K18 and causes its lifting arm K21 to raise the tail of the actuating-plate AP3. The raising of the tail of AP3 causes the following six actions before the plate begins to travel rearward in the machine on its forward stroke (Fig. 20).

1. The beveled portion of the actuating-plate enters the pendants AP13 and spreads them so that no other actuating-plate can be raised.
2. The actuating-plate lifts the ball AP18 which causes the slide AP23 (part of which is shown in section in Fig. 20) to operate the ball-lock F14 so that no digit keys can be operated.
3. The notch AP52 engages the arm M17 of the pitman bracket M14.
4. The notch AP53 engages the arm C39 of the cam rotating slide C38.
5. The nose AP60 engages the flap C157, of the rocking plate C154 and swings the plate idly counter-clockwise against the tension of spring C158.
6. The tail of the actuating plate contacts the portion M38 of the rocking plate M35 and swings the plate counterclockwise against the tension of its spring M36. This causes the rocking plate M35 to contact and swing the motor-control bail M26 counter-clockwise so that the single-revolution motor-clutch becomes engaged and the motor begins driving the pitman bracket toward the rear of the machine.
7. The plate AP3, due to the engagement of the notch AP52 with the arm M17 of the pitman bracket, moves rearward in the machine and carries with it the cam-rotating slide C38 of which the arm C39 is a part. The initial part of the forward stroke of the actuating-plate AP3 causes its nose AP60 to release the rocking plate C154 which immediately swings to its normal position. At about this time, the cams C24 begin to rotate and those cams, which have been depressed, begin to swing their associated sec-

tors S. Soon thereafter, the plate AP3 picks up the lug C180, of the carriage-return arm C110 and begins cocking this arm. Soon after this, the tooth AP63 engages the U-shaped rock-lever P32 and begins to swing it counter-clockwise to cock the hammers P26. At the end of the forward stroke, the raised portion AP34 contacts the bail A79 and throws the upper accumulator into mesh, the sectors S are fully positioned and the type hammers are released. The number printed is 37.58. The digits 62 are not printed after the amount 37.58 because, on the present machine there are only two hammers P26 to the right of the decimal point line.

On the return stroke of the plate AP3 the tooth AP63 returns the rock-lever P32 and thus allows restoration of the printing mechanism; the cams C24, and consequently the sectors S are returned to zero position thus adding the amount 37586200 into the upper accumulator; near the end of the return stroke, the nose AP60 contacts the flap C187, of the rocking plate C184, and swings the plate clockwise to effect a swinging of the escapement rack C10 to its E1 position and return of the carriage, the carriage being cleared as it returns to home position; and at the end of the return stroke, the cam surface AP35 throws the upper accumulator out of mesh with the racks S1. The tip AP28 of the tail of the actuating plate which has contacted, and swung clockwise, the portion M38 of the rocking plate M35, causes the plate M35 (at the very end of the return stroke) to restore the motor-control bail M26 and thus disengage the single-revolution motor-clutch. The tail of the actuating plate then drops releasing the rocking plate M35 which then swings, under spring tension to its normal position.

If it had been desired to enter the amount in the lower accumulator the procedure would have been the same as that just outlined except that the accumulator shift key K1 would have been moved to the right just before the palm bar K3 was depressed. This would have shifted the rock-lever K20 two steps to the right so that its lifting arm K21 would have been positioned under the tail of the grand-addition actuating-plate AP6. Thus, the amount would have been entered into the lower accumulator instead of the upper.

In subtraction, the digit-key set up is the same as outlined for addition and the operation of the back-space key is also the same. After the back-spacing has been completed, the subtraction palm-bar K2 is depressed. This causes raising of the tail of the subtraction plate AP4. The action of the plate AP4 is the same as that of the plate AP3 with one exception. Referring to Fig. 30, the plate AP4 is so constructed that, in the initial part of its forward stroke, the lug AP38 throws the upper accumulator into mesh so that, as the sectors rise, they turn the accumulator wheels in the opposite direction to that in which they are turned in adding. At the end of the forward stroke, the cam surface AP37 throws the wheels out of mesh.

If it be desired to subtract an amount from the lower accumulator, then, before the palm-bar K2 is struck, the accumulator-shift key K1 is moved to the right. This moves the lifting-arm K22 (Fig. 44) two steps to the right so that it is positioned under the tail of the plate AP6 instead of under the tail of the plate AP4. Subsequent depression of palm-bar K2 subtracts the amount from the lower accumulator.

TOTALING MECHANISM

Totaling position of cam carriage

In taking totals (and this includes sub-totals), the cam carriage is drawn to the right of the sectors S, so that the carriage stepping-dog rests upon the right-hand end of the escapement rack, before the actuating-plate moves rearward in the machine. The means for drawing the carriage to its right-hand or total taking position will now be described. Referring to Figs. 18, 19, and 63, a long lever C185 is pivoted upon a shoudered screw C186 which threads into the actuating-plate frame-wall F22. An expansion spring C187 is coiled about the head of the screw C186 and is anchored, at one end over the upper edge of the lever C185, and at its opposite end, to the frame wall F22. The spring tends constantly to urge the lever C185 counter-clockwise, as seen in Fig. 18. As is best seen in Figs. 19 and 63, the front end of lever C185 is bent leftwardly so that it passes through a slot C188, in the frame wall F22 and overlies the tails of the five actuating plates AP7—AP11 (inclusive). Thus, whenever the tail of one of these five actuating-plates is lifted, it contacts the bent-over front end of lever C185 and swings the lever clockwise (as seen in Fig. 18). Referring to Fig. 45, the lever C185 is formed with a cam point C189 at its rearward end. This point is for cooperation with the rightwardly bent end C190 (see also Fig. 19) of a short link C191. The link C191 is pivoted upon the rearwardly extending end of a rock-lever C192. The lever C192 is pivoted upon a countersunk rivet C193 which rivet is fast in the actuating-plate frame wall F22. The lever C192 is formed with a downwardly extending cam-surface C194. The rear end of the lever C192 is connected to one end of a toggle-spring C195, the other end of which is anchored to a headed rivet C196 which rivet is fast in the frame wall F22. From the foregoing, it is seen that as the tail of any of the actuating-plates AP7—AP11 rises, the tail swings the lever C185 clockwise (see Fig. 45) and the point C189, thereof, acts upon the end C190 of link C191 and swings the rock-lever C192 clockwise. The toggle spring C195 normally rests in such a position that, as soon as the link C191 is pulled down a short distance, it takes effect on lever C192 and urges the link C191 to its lower position with a decided snap. As can be seen in Figs. 15 and 18, the rightwardly bent end C190, of link C191, rides in a slot C197 in the frame wall F22. The slot C197 is formed with a cam surface C198 and thus, as the link C191 moves downward, the forward edge of the end C190 strikes the cam surface C198 and is thus cammed free of the point C189 of the lever C185. Referring particularly to Fig. 15, the carriage-return arm C108 (as was previously explained) is made with a leftwardly bent lug C126 thereon. This lug extends into the plane of the end C190 of the link C191 and normally underlies C190 as is shown. Regardless of how far, toward the left-hand side of the machine, the cam carriage may be positioned, the lug C126 always underlies the end C190 of link C191. Thus, whenever the link C191 is pulled down, the end C190, thereof, contacts the lug C126 and rotates the carriage-return arm C108 clockwise (as seen in Fig. 15) which pulls the carriage to its extreme right-hand position wherein the stepping dog C15 (Fig. 49) rests against the rightmost tooth of the escapement rack C10. During the rightward movement of

the cam carriage, the escapement rack C10 remains in its normal or E2 position so that the stepping dog C15 ratchets past the teeth thereof.

Sector swinging

After one of the tails of the actuating-plates (AP1—AP11) has been raised and the cam carriage has thus been drawn to the right and out of engagement with the sectors S, the actuating-plate begins to move rearward, in the machine, on its forward stroke. Referring to Fig. 45, all the plates AP1—AP11 are equipped with upright ears AP65. At the first part of the forward stroke, the ear AP65 engages a long rightwardly projecting arm S20 which arm is for effecting swinging of the sectors S during total taking operations. Referring to Figs. 27, 45 and 47, the arm S20 is an integral part of a lever S21 which lever is pivoted upon the right-hand side of the shaft S13. Fast upon the right-hand end of shaft S13 and adjacent to the lever S21 is an arm S22. Pivotedly mounted upon the upper end of the arm S22 is a pawl S23 which holds a rightwardly protruding pin S24 therein. The pawl S23 is threaded to receive a screw S38 which passes through a hole in the arm S22. Thus, the pawl S23 and screw S38 turn, at certain times as a unit. An expansion spring S25 is coiled about the grooved head of screw S38 and one end of the spring is anchored, as shown, to the arm S22 while the opposite end of the spring is anchored to the pawl S23. The spring S25 tends, constantly, to urge the pawl S23 in a clockwise direction as seen from the right-hand side of the machine. The pawl S23 lies in the plane of the lever S21 and, in its normal position shown in Fig. 45, a tooth S26, on the pawl, engages a shoulder S27 on the lever S21. The pawl S23 is formed with a notch S28, therein, which notch is for cooperation with a pin S29. The pin S29 extends rightwardly from the arm F82 of the sector hanger and is fast therein. A spring S30 (Fig. 47) is coiled about the shaft S13 and lies adjacent the inside of the arm F82. One end of the spring S30 is anchored to the sector-hanger arm F82 and the other end of the spring is anchored in a notch S31 which notch is formed in the lower end of the lever S21. The spring S30 tends constantly to urge the arm S21 counter-clockwise, as seen in Figs. 45 and 47, the counter-clockwise motion of lever S21 being limited by the pin S29. The operation of the sector-swinging parts during a total cycle is as follows: On the initial part of the forward stroke, the ear AP65 (Fig. 45) engages the arm S20, of lever S21, and begins to swing the lever clockwise. Due to the engagement of the pawl S23 and the shoulder S27, the lever S21 carries with it the pawl S23 and, consequently, begins rotating the arm S22 clockwise. This rotates the shaft S13 (see Fig. 22) clockwise and thus rotates the flat spring S15 causing its fingers S16 to swing the sectors S in a counter-clockwise direction. Due to the loose engagement of the spring-fingers S16 and the lugs S17, on the sectors, and due to the inertia of the sectors S, a time-lag is allowed between the initial movement of shaft S13 and the actual swinging of the sectors so that the accumulator-wheels may be meshed with the actuating racks S1 before the sectors start to move. Continuing with the forward stroke of the actuating-plate, at about the middle of the forward stroke, the notch S28, of pawl S23 (see Fig. 47), engages the pin S29 and the pawl is cammed slightly counter-clockwise so that its point S26

becomes disengaged from the shoulder S27 and rides a cam surface S32, on the lever S21. This locks the pawl S23 and arm S22 in the position shown in Fig. 47 and at this time the sectors S have been swung to the limits of their various movements. Just prior to the end of the forward stroke, the lever S21 is carried (clockwise) past its Fig. 47 position so that the cam surface S32 passes out of engagement with the point S26, of pawl S23, and releases the pawl. The spring S14 (Fig. 22) then takes effect upon the shaft S13 and begins to return the shaft and the arm S22 and pawl S23 to their normal positions. However, due to the fact that the spring fingers S16 are bowed, an element of time is introduced before the sectors begin their return. During this time, printing occurs and directly, thereafter, the sectors move under the reversed action of the spring-fingers S16. The sectors are thus returned to their normal positions before the actuating-plate has completed its return stroke. On the return stroke, the lever S21 follows the ear AP65 of the actuating-plate under tension of the spring S31 (Fig. 27) and the surface S32, of lever S21 contacts the pawl S23 and cams it slightly counter-clockwise. The pawl then idly rides the surface S32 until the lever S21 has completed its return movement, at which time, the point S26 of the pawl S23 reengages the shoulder S27 of lever S21 and the parts resume their normal position shown in Fig. 45.

Setting the zero stops

The zero stops A60 (Figs. 1 and 2) are set by means of the levers A62 and the means for actuating the levers A62 during a total cycle of the machine will now be described. Referring to Figs. 20, 21, and 45, there are pivotally mounted, in the paths of the actuating-plates, two ball-shaped rock-levers A90 and A91. Each rock-lever (see particularly Fig. 21) is formed with a cross-portion A92, a forwardly extending foot A93 and a pair of supporting-lugs A94 thereon. When the rock-levers A90 and A91 are mounted in the machine, the left-hand supporting lugs A94 are journaled in V-shaped slots A95 (Figs. 20 and 45) in the frame A15 and the right-hand lugs A94 are journaled in V-shaped slots A96 in the frame F26 (Fig. 18). The cross portion A92, of the rock-lever A91, passes through slots AP70 (Fig. 45) cut in the actuating plates AP1 to AP11 (inclusive). The slots AP70 of all the actuating-plates except those of the grand-total taking plate AP11 and the grand-sub-total taking plate AP8 are of such a size that, even when the tails of the plates are raised, the plates do not move the rock-lever A91. When, however, the tail of either plate AP11 (Fig. 37) or AP8 (Fig. 34) is raised, a surface AP11, thereon, contacts and raises the cross-portion A92 of rock-lever A91 and thus swings the rock-lever clockwise (as seen in Fig. 45). The swinging of the rock-lever A91 raises its foot A93 which, in turn, raises the end A63 of the lever A62 (Figs. 1 and 2) associated with the lower accumulator and thus swings the zero stop A60 (Fig. 2) into the paths of the blocks A31 on the accumulator-wheels A13 of the lower or grand-total accumulator. The zero stop A60 for the upper accumulator is set in much the same manner as that of the lower accumulator. The three plates AP7 (sub-total) (Fig. 33), AP9 (transfer-total) (Fig. 35), and AP10 (total) (Fig. 45) are all formed, as is best shown in Fig. 45, with a surface AP72 which surface, on these three plates only, is so positioned that it lies in a

plane above that of the cross-portion A92 of the rock-lever A90 whenever the tail of any of the three actuating-plates is raised. Hence, on the forward stroke of any of the plates AP7, AP9 or AP10, the cross-portion A92, of lever A90, is cammed up onto the surface AP72 thus setting the zero stop associated with the upper accumulator.

Summary of machine operations during a total cycle

The machine operations are most easily seen by following the movements of one of the plates AP7—AP11 through a complete cycle. The plate AP10 is, therefore, chosen for illustration as it is shown in Fig. 45. Assume that the total-selecting lever K8 (Fig. 44) has been set so that the lifting-arm K24 underlies the tail of the plate AP10. Then depression of the total taking palm-bar K5 raises the tail of the plate AP10 and causes seven actions just as the raising of the tail of the addition plate AP3 (Fig. 20) causes six. These actions are as follows:

1. The beveled portion of the actuating-plate tail enters the pendants AP13 (Fig. 20) and spreads them so that no other actuating-plate can be raised.
2. The actuating-plate lifts the bail AP18 (Figs. 20 and 45) to operate the ball-lock F14 (Fig. 20) so that no digit key can be operated.
3. The notch AP52 (Figs. 20 and 45) engages the arm M17 of the pitman bracket M14.
4. The notch AP55 (Fig. 45) engages the arm C38 of the cam-rotating slide C38.
5. The actuating-plate tail contacts the leftwardly bent forward end of the lever C185 (Fig. 45) and swings the lever C185 clockwise which results in the cam carriage being drawn to its totaling position.
6. The nose AP60 engages the flap C157 (Fig. 20) of the rocking plate C154 and swings the plate idly.
7. The tail of the plate AP10 contacts the rocking-plate M38 (Fig. 20) and swings it causing engagement of the single revolution clutch.

In the initial part of the forward stroke, the surface AP72 of the plate AP10 (Fig. 45) sets the zero stop for the upper accumulator; the lug AP30 throws the accumulator into mesh with the actuating racks; and the ear AP65 contacts and moves the arm S29 thereby swinging the sectors S. Near the middle of the forward stroke, the pawl S23 (Fig. 45) engages the pin S29 and the plate AP10 picks up the lug C130 and begins cocking the carriage-return arm C110. Near the end of the forward stroke, the pawl S23 is released and also a cam-edge M20 (dotted in Fig. 45), of the pitman bracket M14, contacts the surface C194, of lever C192 and restores the lever to its normal position. At the end of the forward stroke, the total is printed and the upper accumulator is thrown out of mesh by cam surface AP31. At this point, it is to be understood that due to the fact that the cam carriage has not escaped into the path of the sectors the rotation of cams C24 performs no function during the present total taking cycle and it is further to be understood that, when the plates AP10 or AP11 are used, the plates do not positively restore the cams C24 to zero position. The cams C24, in this instance, are restored by the spring C42 (Fig. 15) attached to the cam-rotating slide C38. On the return stroke, the nose AP60 performs its regular function but due to the fact that the cam carriage is in its rightmost position, the action

of the carriage-return arms C108 to C110 is ineffective except that the escapement rack is swung to its lowest or E1 position. This causes clearing of the carriage and allows the spring C92 (Fig. 49) to draw the carriage leftward to its home position. The carriage-clearing action just mentioned is usually idle but if the operator had inadvertently set up an amount in the cams C24 and then depressed the total taking palm-bar, the carriage would be cleared of the amount at the end of the total cycle. While the movements of the carriage-return arms C108—C110 (inclusive) are idle, with the noted exception, still they afford a timing element by causing the latch-plate C134 to be held in its operated position until after the cam carriage has returned to its home position. Due to the particular accumulator used and to the use of the zero stops A60, no blank stroke is necessary before a total cycle.

MULTIPLICATION AND DIVISION

Multiplication is accomplished on the present machine by a process of repeated addition and, in multiplication, the digit keys are used to cycle the machine. A multiplication key K1 (Fig. 11) is operated to convert the digit keys to motor-control keys and the regular actuating-plate pendant-lock is automatically brought into play, during multiplication cycles, so that no palm-bar can be depressed. Referring particularly to Figs. 14 and 64, it is seen that there is pivotally mounted, upon the left-hand upright arm of the U-shaped actuating-plate frame F22, a bell-crank lever AP75 which has an upright arm AP76 and a forwardly extending arm AP77. The upper end of the arm AP76 is slotted (Figs. 14 and 78) at AP78. Normally resting in the lower end of the slot AP78 (see Fig. 64) is a leftwardly extending lug AP79 which lug is integral with the slide AP24. The slide AP24 is mounted, upon the screws F51, between the cross-brace F50 and the slide AP23 (see Fig. 65). The forwardly extending arm AP77 of the bell-crank AP75, is bent rightwardly into a lug AP80 (Fig. 64) and the lug AP80 engages in the slot in the tail of the multiplication actuating-plate AP1, as shown (see also Fig. 78). Thus, whenever the slide AP24 is raised, the lug AP79, thereon, moves upward in the slot AP78 and cams the arm AP76 toward the rear of the machine. This raises the lug AP80 and thus raises the tail of the multiplication actuating-plate AP1. As is seen in the lower part of Fig. 64, the bail AP18 is cut away so that the tail of the plate AP1 does not, when raised move the bail. The means for raising the slide AP24 is a converter-bar or slide X1 which bar is mounted for lateral sliding movement upon the front of the cross-brace F50. Referring particularly to Figs. 64 and 65, the converter-bar is slotted at X2 and shouldered screws X3 pass through the slots X2 and thread into the cross brace F50. A spring X4, anchored at one end in a hole in the converter-bar X1 and anchored at its opposite end to the arm K53, tends constantly to draw the converter-bar toward the left-hand side of the machine. The converter-bar X1 is offset toward the front of the machine at X5 and is then bent upward to form an upright portion X6. At its left-hand end, the portion X6 is formed with an inclined cam surface X7. The right-hand end of the portion X6 is bent forwardly into a lug X8 against which rests the depending arm of the bell-crank K8. Thus, whenever the multiplication lever K1 is moved clockwise, it contacts and swings the bell-crank

K8 counter-clockwise and the depending arm of the bell-crank K8 moves the converter-bar X1 to the right the full distance permitted by the slots X2. Fast in the converter-bar X1 is a pin X9 which pin passes through a horizontal slot X10 in the cross-brace F50 and enters an inclined slot X11 in the slide AP24. Thus, whenever the converter-bar X1 is moved to the right, the pin X9 cams the slide AP24 upward. As the slide AP24 rises it enters between the balls of the digit key ball lock and prevents the depression of a digit key while the multiplication lever K7 is being swung. The rearwardly extending finger AP25 of the slide AP24 is cut away, as is best shown in Fig. 18 so that, after the slide AP24 has risen to its full extent, the finger AP25, thereof lies above the balls and thus the balls are released to allow depression of the digit keys. From the foregoing, it is evident that, if a digit key is depressed, the multiplication lever K7 cannot be actuated and, if the multiplication lever K7 is first actuated and then a digit key is depressed, the converter-bar cannot be returned to normal until the digit key has returned. Thus there has been provided an interlock between the multiply key K7 and the digit keys. The converter bar X1 (Fig. 64) is formed, near its middle, with an inclined cam-surface X12. This cam-surface (see Fig. 15) lies in a plane with a portion C69 of the depressor hook C49. Therefore, whenever the converter-bar is moved to the right, the cam-surface X12 swings the depressor hook C49 (Fig. 15) slightly counter-clockwise to an inactive position. In this inactive position even though the bell-crank C54 (Fig. 15) is moved, the finger C56, thereof will not contact the depressor hook. Thus the clutch-plate K58 and universal bar K51 are free to rotate without swinging the depressor hook. Referring to Figs. 14, 64 and 65, there is pivotally mounted upon a screw F54 fast in the left-hand motor frame-wall F18 (Fig. 14), a motor-control rack-segment X13. Pivotally mounted upon a shouldered screw X14 (Figs. 14 and 65), which screw is fast in the top of the segment X13, is a link X15. The link X15, as is particularly well shown in Figs. 14 and 64, is formed near its middle with a rightwardly bent lug X16 which lug normally rests upon the upright portion X6 of the converter-bar X1. An expansion spring X17 (Fig. 65), coiled about the head of the screw X14, is anchored at one end to the link X15 and at its other end to the top of the motor-control segment X13. The spring tends constantly to urge the link X15 counter-clockwise as seen from the left-hand side of the machine. The link X15 (see Fig. 14) is formed with a rearwardly extending hook X18 thereon which hook normally overlies the top of the universal bar X51, as shown. Whenever the converter-bar X1 is moved to its rightward position in the machine, the cam-surface X12 moves away from the lug X16, of link X15, and allows the link to pivot under tension of the spring X17 until the hook X18 engages the top of the universal bar. In summation, when the multiplication lever K7 (Fig. 64) is operated, it actuates the bell-crank K8 which moves the converter-bar X1 to the right. This movement of bar X1 causes the motor-control segment X13 to be coupled to the universal bar K51. It also causes the depressor hook C49 to be disabled, the digit key ball-lock to be operated and released, and the tail of the multiplication actuating-plate AP1 to be raised. The plate AP1, unlike the rest of the actuating-plates,

does not cause cycling of the machine when its tail is raised as will now be explained. Referring to Figs. 78 and 79, the tail of the multiply plate AP1 is of special construction and due to this construction, when the tail is raised from its normal Fig. 78 position to its Fig. 79 position, the rocking plate M35 is not rocked. In multiplication, the motor-control bail M26 is tripped by the segment X13 as will now be described.

Referring particularly to Figs. 14 and 14A, the disc M34, to the inside of which the motor-control bail M26 is fastened by the screws M33, is formed with a tooth M44 which tooth is integral with the disc M34 and is struck-out leftwardly therefrom. Mounted for rotation upon a headed rivet M45, which rivet is fast in the disc M34, is a pawl M46 which is made with noses M47 and M48. A spring M49, anchored at one end to a hole in the disc M34 and anchored at its other end to the pawl M46, is coiled about the head of the rivet M45 and tends constantly to urge the pawl M46 counter-clockwise as seen from the left-hand side of the machine. Normally, the nose M47, of pawl M46, rests against the top of the uppermost or first tooth of the motor-control segment X13 (the bottom tooth being the eleventh) and the nose M48, of pawl M46, is out of contact with the tooth M44 of disc M34. As is best seen in Fig. 14, the motor-control segment X13 is constantly urged clockwise by a contractile spring X20 which spring is anchored, at one end, over a shoulder of the segment X13 and is anchored, at its opposite end, in a hole in the frame wall F18.

Assume, for example, that it is desired to multiply the amount 1356 by 73 and assume, further, that the machine is clear. The operator first sets up the amount 1356 on the digit keys by depressing first the "1" key, then the "3" key, etc. The operator then swings the multiplication key or lever K7 toward the right-hand side of the machine. This raises the slide AP24 (Fig. 64) up through the balls of the digit key ball-lock so that the finger AP25 lies within the ball hanger but is above and clear of the balls. Actuation of the multiplication lever K7 also disables the depressor hook C49, raises the tail of plate AP1 from its Fig. 78 position to its Fig. 79 position and couples the segment X13 (Fig. 14) to the universal bar K51. The operator is now ready to insert the multiplier 73 into the machine. Holding the multiplication lever K7 actuated the "3" digit key is depressed. This rocks the universal bar K51 three steps counter-clockwise from its Fig. 14 position which, in turn, rocks the segment X13 counter-clockwise so that the three uppermost teeth, thereon, ratchet past the point M47 of the pawl M46. The operator then releases the "3" digit key and three add cycles of the machine occur as follows: As soon as the operator has released the "3" digit key, the key begins to rise and the spring X20 (Fig. 14) urges the segment X13 clockwise so that the third tooth, thereof, presses down on the nose M47, of pawl M46 and swings the pawl and its disc M34 clockwise to the Fig. 14A position wherein the nose M48 comes to rest against the tooth M44 and the tooth M44 engages the under side of the fifth tooth on the segment X13. In this position of the disc M34, the motor-clutch is tripped and the actuating-plate AP1 moves toward the rear of the machine. As it does so, its tail releases the rocking plate M35 (Fig. 80) which then swings back to its normal position. Thus, the parts appear as is shown in Fig. 80 at the

end of the forward stroke. On its return stroke, the tip AP28, of the plate AP1, contacts the portion M38, of the rocking plate M35, and swings the plate clockwise thus restoring the motor-control ball M28. As is seen in Fig. 81, which shows the position of the parts at the end of the return stroke, when the plate AP1 has returned to its full extent, the tip AP28 releases the rocking plate M35 and, due to the shape of the tail of the plate AP1, the rocking plate M35 is allowed to return to its normal position (see Fig. 79). Thus, at the end of the first cycle, the actuating-plate AP1 has swung the disc M34 from the Fig. 14A position back to Fig. 14 position and the nose M41, of pawl M46, then lies in contact with the under side of the second tooth of the segment X13. Thus the segment has swung clockwise one tooth-step during the first multiplication cycle and this has allowed the universal ball K51 to return part way and has, therefore, allowed the "3" digit key to rise one-third of its depressed distance. Also the amount 1356 has been added into the upper accumulator. It is to be noted at this point that the nose AP60 (see Fig. 26), of plate AP1, is smaller than the noses AP60 of the other actuating-plates and, as a result, no carriage return is effected until the tail of the plate AP1 drops to its normal position. The tail of the plate AP1 cannot drop until three machine cycles have occurred due to the fact that the "3" digit key cannot fully rise until the end of the third cycle.

As soon as the rocking plate M35 (Fig. 81) is released at the end of the first cycle, the spring X20 (Fig. 14) again takes effect and the second tooth of the segment X13 acts upon the nose M41, of pawl M46, and swings the disc M34 to its Fig. 14A position so that the tooth M44 contacts the under side of the fourth tooth on segment X13 and another machine cycle follows. In this second multiplication cycle, the amount 1356 is again added into the upper accumulator. The third cycle is a repetition of the first two but at the end of this cycle, the "3" digit key rises to its normal position and this causes an escapement of the cam carriage to the left. Due to the fact that the operator still holds the multiplication lever K1, the tail of the actuating-plate AP1 does not drop and, hence, no normal carriage return occurs. The operator now depresses the "7" digit key and seven add cycles follow automatically. At the end of the last cycle, the operator releases the multiplication lever K1 which allows the tail of the plate AP1 to drop and the nose AP60 to swing the rocking plate C154 (Fig. 20) clockwise. This causes the return of the cam carriage and the carriage is cleared by the escapement rack C10 as it returns. No printing occurs during multiplication cycles because the plate AP1 has no printing teeth AP62 or AP63 thereon (see Fig. 26). Thus, at the end of the last multiplication cycle, the product 98988 has been entered into the upper accumulator. This may be transferred to the lower accumulator, if desired, by setting the total-selecting lever K6 for a transfer total and then depressing the total palm-bar K5.

The use of the back-space key, as applied to the accomplishment of multiplication problems on the present machine is quite simple and is best understood by specific illustration. For example, assume that it is desired to multiply 3.3527 by 7.12. The only things that the operator must remember about back-spacing the carriage are the following two points.

1. The carriage must be back-spaced once for every digit, over two, which is to the right of the decimal point of the multiplicand.

2. The carriage must be back-spaced once for every digit in the multiplier before the multiplier is entered in the machine. The method of operating the machine to compute the above given problem is as follows: The operator depresses the digit keys "3," "8," "5," "2" and "7" in that order. Due to the fact that there are four digits to the right of the decimal point, in the multiplicand 3.8527, the operator, at this time, back-spaces the carriage twice. Looking at the multiplier 7.12, the operator notes that there are two digits to the right of the decimal point and, therefore, back-spaces the carriage two more times. The operator then operates the multiplication lever and depresses the "2," "1" and "7" digit keys in that order and then releases the multiplication lever. The accumulator wheels then read 0000027431224. The operator then depresses the total palm-bar K5 and the machine prints the product 27.43. The reason why the digits 1224 are not printed is that there are no printing hammers associated with these digits as was explained in detail under the heading "The printing section."

Division on the present machine, is accomplished by the use of reciprocals. Thus, division 30 is actually accomplished by a multiplication process. Assume that it is desired to divide .78 by 4. The reciprocal of four is .25. Thus, the operator sets up .78 on the digit keys, back-spaces the carriage twice and multiplies by "5" and "2." The 35 resulting quotient on the accumulator wheels reads 0000000195000 and, if totaled, the machine prints .19.

REMULITIPLY MECHANISM

40 The remultiplication mechanism of the present machine is not a mechanism for remultiplication a previous product by a new multiplier in one cycle of operation but is really a mechanism for withdrawing a total, from either accumulator and impressing that total upon the cams of the cam carriage during one machine cycle so that the total, thus impressed, may, on subsequent cycles, be multiplied by a given multiplier. In 45 order to extract a total from the upper accumulator and impress it upon the cams, it is only necessary to depress the remultiplication key K11. If it is desired to extract a total from the lower or grand-total accumulator and impress it upon 50 the cams, then the grand-re-multiplication key K12 is first depressed and held and then the remultiplication key K11 is depressed. Thus it is seen that, using the remultiplication mechanism, a number may be successively multiplied by a 55 series of different multipliers with very little mental effort being necessary on the part of the machine operator to remember the manual operation of the machine.

In order to accomplish extraction of a total 60 from an accumulator and impression of the total upon the cams of the cam carriage and in order to retain the total in the cams and to have the carriage in a correct position at the end of a re-multiplication cycle, it is necessary that the re-multiplication mechanism be such that it will 65 act to comply with the following requirements:

1. The carriage must be tabulated to the left and must be stopped in such a position that the first or leftmost cam C24 is aligned with the first 70 or leftmost sector S. Also a carriage-clearing

operation must have occurred by the time that the tabulating operation is finished. This clearing operation is usually an idle one but is a means for insuring that the carriage is clear at the beginning of a re-multiplication cycle. It is also to be understood that the clearing and tabulating of the carriage must be accomplished before an actuating-plate begins its forward stroke.

2. The cams C24 must be rotated 90° before the beginning of the forward stroke of the actuating-plate so that they will be in position to be depressed by the heels of the sectors S.

3. The means for locking the cams, during their rotation, must be disabled so as to permit them to be depressed by the sector-heels.

4. The means for drawing the carriage to its rightmost or totaling position must be disabled before the forward stroke begins.

5. The re-multiplication key must be locked against depression unless the carriage is in its home position.

6. The re-multiplication key, after it has been depressed, must be fully returned to its normal position before the actuating-plate begins its forward stroke.

7. As soon as the re-multiplication key is depressed, the multiplication lever, palm-bars and digit keys must be locked against operation.

8. After the above seven requirements have been met, the actuating plate must move through its cycle and swing the sectors S as in a regular totaling cycle. The sector movements impress upon the cams C24, the total held in the associated accumulator.

9. The carriage-return mechanism must be disabled.

10. The carriage-clearing mechanism must be disabled during the cycling of the machine in re-multiplication operations.

Referring to Figs. 72 and 73, it is seen that, riveted to the pulley C113 which turns with the movements of the cam carriage, there is a stamped gear RX1. This gear RX1 is equipped with a plurality of teeth RX2 which teeth are bent upwardly at right angles to the body of the gear RX1. The gear is also formed with a special tooth RX3 which tooth projects radially from the gear RX1. Referring to Fig. 68, the gear RX1 is indicated in dot-dash lines and is shown in its normal position. The gear RX1 assumes its normal position when the carriage is in its home position. In the normal position of gear RX1, the tooth RX3 rests as shown against the forwardly extending arm RX5 (dotted lines) of a bell-crank RX6. The bell-crank RX6 is pivotally mounted upon a shouldered screw RX7 which screw is fast in the cross-portion F57 of the frame F55. The arm RX5 is offset (see also Fig. 69) so as to bring its front end into the plane of the tooth RX3 on the gear RX1. The bell-crank RX6 is formed with a leftwardly extending arm RX8 (Fig. 68) which has a slot RX9 cut therein. A small shouldered rivet or screw RX10 passes through the slot RX9 and fastens in the cross-portion F57. The bell-crank RX6 is formed also with a rearwardly extending arm RX11, as is shown in both Figs. 68 and 69, which arm is bent downwardly near its rear end. A spring RX12 (Figs. 68 and 69) is coiled about the head of the screw RX7 and is anchored, at one end to the arm RX11. At its opposite end, spring RX12 is anchored to the frame wall F55. The spring tends constantly to urge the bell-crank RX6 to the position shown in full lines in Fig. 68. In

this position, the left end of the arm RX8 underlies the bottom of the re-multiplication key K11 and thus locks the key against depression. However, when the carriage is in its home position, 5 the tooth RX3, of gear RX1, holds the bell-crank RX6 in its normal position (shown in dotted lines in Fig. 68) and, in this position, the left end of the arm RX8 does not underlie the stem of key K11. Thus it is seen that whenever the cam 10 carriage is in its home position, the key K11 is free to be depressed but when the carriage is in any other position the tooth RX3, of gear RX1, does not hold the bell-crank RX6, and, consequently, the spring RX12 holds the bell-crank in 15 its abnormal position so that the left end of arm RX8 locks the key K11 against depression.

The means for causing the carriage to tabulate and clear will now be described. Referring to Figs. 66, 67, 68, 69, and 82, the stem of the key 20 K11 overlies a cam RX14 which cam is pivotally mounted upon the shaft F75 and lies adjacent the right-hand side of the slide C150. As is best shown in Fig. 69, wherein all parts are shown in normal position, the cam RX14 is formed with an ear RX15, a locking-surface RX16, a nose RX17, a cam-surface RX18, a cam-point RX19 and a rightwardly bent lug RX20 thereon. The cam RX14 is yieldingly held in its normal position, wherein it limits against the cross-portion 25 F57, of frame F55, by means of spring RX21 (Figs. 66, 67, and 68). Spring RX21, coiled about the shaft F75, is anchored at one end to the front of the lug RX20 and is anchored at its opposite end to the rear edge of a cross-portion 30 RX22 of a bail-shaped cam RX23. The normal position of cam RX23 is as shown in Fig. 66. Thus, it is seen that the spring RX21 constantly tends to press the lug RX20 against the front of the cross-portion RX22, of cam RX23. The 35 cam RX23 (Figs. 66, 67, and 68) is pivotally mounted upon the shaft F75 and lies adjacent the right-hand side of the cam RX14. Cam RX23 is yieldingly held in its normal or Fig. 66 position by means of an expansion spring RX24 which is coiled around the shaft F75. One end of the spring RX24 is anchored to the front of the cross-portion RX22, of cam RX23, and the other end is anchored to the rear of the cross-portion 40 F57, of frame F55. Referring to Figs. 68 and 69, it is seen that a cross-shaft F76 is mounted in the same way as the shaft F75. The shaft F76 is threaded at its left-hand end and is screwed into the ear F59. Pivotally mounted upon shaft F76 is a rock-lever RX26 (Figs. 68, 45 69, and 70) the upper part of which lies in the same vertical plane as the cam RX14. The rock-lever RX26 is offset toward the left-hand side of the machine so that its tail RX25 (Figs. 69 and 70) lies flush against the framing ear F59 and thus the tail RX25 lies directly under part 50 of the slide C150. An expansion spring RX100 (Figs. 68 and 70) which is coiled about the shaft F76, is anchored at one end to the framing-ear F59 and is anchored at its other end to the rock-lever RX26. This spring RX100 tends constantly 55 to urge rock-lever RX26 counter-clockwise, as seen from the right-hand side of the machine. A flap RX27 (Figs. 68, 69, and 70) is bent around the shaft F76 and is adapted to pivot thereupon. 60 The flap RX27, as is best seen in Fig. 70, is so shaped that it passes leftwardly under the rock-lever RX26 and into a V-shaped slot in the slide C150. The flap RX27 (Fig. 69) is yieldingly urged 65 against a projection RX28 formed on rock-lever RX26 by a spring RX29 which is coiled about 70 75

shaft F16. One end of spring RX29 is anchored to the back of the flap RX28 and the opposite end of the spring is anchored under a rearwardly extending projection RX30, on the rock-lever RX26. Thus, flap RX27 tends, at all times, to follow the movements of rock-lever RX26. The rock-lever RX26 is formed with a shoulder RX31 on its rear edge which shoulder, as is best seen from Figs. 74, 75, and 82, is adapted, at certain times, to be engaged by a rightwardly bent lug RX32 of a rock-lever RX33. The lever RX33 normally rests, by gravity in the position shown in Fig. 75, that is, its lug RX32 limits against the lower edge of the rock lever tail RX25. The lever RX33 is pivoted at RX34 upon the left-hand side of the framing-ear F59. The forward end of rock-lever RX33 (see Figs. 67 and 74) is slightly offset toward the left of the machine so that it lies above and in the path of the flap C151, of the rocking-plate C154. Referring to Figs. 66 and 67, the bail-shaped cam RX23 is formed with a leftwardly bent lug RX37 thereon which lug normally rests on top of a lug RX38 of a latch RX39. The latch RX39 is pivoted upon a shouldered, countersunk rivet RX40 which rivet is fast in the upright portion F28 of the actuating-plate frame F22. A coiled contractile spring RX41 is anchored at one end to the lug RX38, of latch RX39, and is anchored at its other end to the grand-re-multiplication key K12. Thus, the spring R41 tends constantly to urge the key K12 upward and also tends to urge the latch RX39 clockwise, as seen in Fig. 66, so that the lug RX38 normally rests against the surface RX16 of the cam RX14. When the re-multiplication key K11 is depressed, it contacts the cam RX14 and swings it to the position shown in Fig. 82. When cam RX14 reaches its Fig. 82 position, the latch RX39 swings slightly counter-clockwise from its normal position so that the lug RX38 is positioned over the ear RX15 and thus the cam RX14 is locked in its operated position. Also, it is seen that in rotating to its operated position, the cam-point RX19 swings the rock-lever RX26 clockwise (as seen from the right-hand side of the machine) until a point RX44, thereon, rides upon a surface RX45, on cam RX14. This movement of rock-lever RX26 causes the flap RX27 to rotate in the same direction which, in turn, moves the slide C150 forward in the machine until the rear end of slot C149 (Figs. 76 and 82) contacts the shaft F17. This forward movement of slide C150 removes the toe C152 from beneath the lug C160 (Fig. 76) on the latch plate C134, and also moves the toe C151 under the right-hand end of the escapement rack C70 and it is to be understood that the complete forward movement of slide C150 is accomplished before the rock-lever RX26 (Fig. 82) has completed its swinging movement. Near the completion of its movement, the tail RX25, of rock-lever RX26, engages the under-edge of the slide C150 and pivots the slide clockwise, as seen from the right-hand side of the machine, so that the toe C151 swings the escapement rack C70 to its uppermost or E4 position which position is indicated in Fig. 56 and shown in Fig. 82. Thus, at the end of the down stroke of key K11, the escapement rack is swung to its E4 position and in this position the escapement-rack teeth are free of the escapement dogs on the carriage so that the carriage immediately begins to tabulate toward the left-hand side of the machine. Referring to Figs. 52 and 57, it is seen that there is fastened to the rear of the escapement rack

C70, and near the left-hand end thereof, a tabulator stop C169. This stop C169 is out of the path of the cam carriage when the escapement rack is in any but its E4 position. When, however, the rack C70 is swung to its E4 position, the stop C169 is positioned directly in the path of the lug C171 of the rocking plate C170. Thus, as the carriage tabulates, the lug C171 strikes the stop C169 and is cammed down thereby so that the carriage frame-plate C4 comes to rest against the stop C169. When the lug C171 is cammed down, the plate C170 is swung counter-clockwise (Fig. 57) to the dotted position and this causes the beveled point C179 to engage and cam inward the locking-slide C34 which, as was previously explained, causes clearing of the cam carriage. Thus it is seen how depression of the re-multiplication key causes tabulating and clearing of the cam carriage. It is to be noted, at this point (see Figs. 74 and 82), that at the bottom of the stroke of the re-multiplication key K11, the rock-lever RX26 having been swung to the full extent of its movement, the lever RX33 swings by gravity so that its lug RX32 engages the shoulder RX31, of rock-lever RX26 and locks the rock-lever in its operated position until the end of the re-multiplication cycle at which time the nose AP60 (Fig. 74) acts upon the flap C151 and swings lever RX33 so as to release the rock-lever RX26 which then returns to its normal position by the action of its associated spring.

The depression of the re-multiplication key and the consequent rotation of cam RX14 is utilized as a means for disabling the lever C185 (Figs. 15 and 66) so that, during the re-multiplication cycle, the carriage will be left in its tabulated position instead of being moved out of cooperative relation with the sectors S, as is the case on the usual total taking cycle. Referring to Figs. 66 and 67, the nose RX17, of cam RX14, normally lies, as shown, slightly below the center of a lamination RX58 which lamination is fast upon the right-hand side of a slide RX51. Slide RX51 is mounted upon shouldered screws RX52 which screws are fast in the right-hand face of the upright portion F28 of the actuating-plate frame F22. The screws RX52 pass through slots RX53 and RX54 in the slide RX51, the slot RX54 being of inverted L-shape. The slide RX51 is constantly urged toward the front of the machine by spring RX55 (Fig. 66 only). Slide RX51 is formed, at its front end, with a leftwardly and rearwardly bent finger RX56 which finger is for cooperation with slots AP51 (Fig. 67), there being one such slot in each actuating-plate AP10 and AP11 (see Figs. 36, 37, and 67). Also the slide RX51 is formed with a nose RX58 at its front end and a rightwardly bent lug RX59 at its rear end. The nose RX58 is for cooperation with the key K12 as will later be explained in detail and the lug RX59 is a means, cooperative with the printing-control lever K13 (Fig. 15), for disabling printing during remultiply cycles. Referring to Figs. 15, 16, and 17, the slide RX51 (Figs. 16 and 17), whenever it is moved rearward in the machine and provided the printing-control lever K13 is in its normal position, contacts, by means of lug RX59, the end K62, of lever K13, and swings the lever to disable the printing clutch-mechanism as was previously explained. If, however, it is desired to make the machine print during a re-multiplication cycle the lever K13 (Fig. 15) is lifted bodily upward and is then latched over the main casting F1. The slide RX51 will then move rearward without

touching the clutch-pawl P40 and, hence, printing will occur at the end of the forward stroke. The slide RX51 is moved rearward as follows: Referring to Fig. 66, on the initial movement of the cam RX14, from its normal position, the nose RX17, thereof, striking the lamination RX50, moves the slide RX51 rearward the full length of the slots RX53 and RX54 and then continued movement of cam RX14 causes the nose RX17 to ride under the lamination RX50 and thus cam up the front end of the slide RX51 so that the top of lamination RX50 is pressed against a surface RX60, of cam RX23. The cam RX14 continues its movement, under action of the key K11, until it limits against the lamination RX50. The rearward movement of slide RX51 causes the finger RX56 to engage in its associated slot AP57 (Fig. 67), in the actuating-plate AP10, and the upward movement of the front end of slide RX51 then causes the tail of the total taking actuating-plate AP10 to be raised slightly but not enough to trip the motor-clutch. Also the rearward movement of slide RX51 causes a downwardly extending tooth RX62 to contact the end C190 (Fig. 66), of lever C191 and swing the lever out of the path of the lever C185 which, as was explained, is actuated on every total taking cycle to pull the cam carriage to its rightmost or totaling position. Thus, the cam carriage will remain in its tabulated position, during a re-multiply cycle, even though the raising of the tail of plate AP10 causes swinging of the lever C185. Summarizing, the rearward and upward movements of slide RX51 effect the following three actions:

1. The disabling of the printing mechanism, if the lever K13 (Fig. 15) is in normal position.

2. The disabling of lever C185 (Figs. 15 and 66).

3. The partial raising of the tail of the actuating-plate AP10. In connection with this action it has been explained that the raising of the tail of any actuating-plate except AP1 causes locking of the digit keys and palm bars of the machine. Thus, at the end of the down stroke of the re-multiplication key, the above three actions have been accomplished, the carriage has been tabulated and cleared and the escapement rack C70 remains in its E4 position. Also, the spring RX21 (Figs. 66 and 67) has been very heavily tensioned and, due to the fact that cam RX14 is latched down, it attempts to move cam RX23 counter-clockwise (as seen in Fig. 66). Since the latch RX39 has moved to its Fig. 82 position, the lug RX38 no longer lies in the path of the lug RX37, on cam RX23, and thus the cam is free to move except for the bell-crank RX6 (Fig. 68). Referring to Figs. 66, 68, and 69, the arm RX11, of bell-crank RX6, is interposed in the path of movement of the cam RX23 whenever the bell-crank RX6 is in its normal position. During a re-multiplication cycle, as soon as the carriage begins to tabulate, the tooth RX3 (Fig. 68) moves away from the arm RX4, of bell-crank RX6, and thus allows the spring RX12 to swing the bell-crank very slightly clockwise from its dotted position so that the end of arm RX8 limits against the depressed stem of key K11. The movement of the bell-crank, however, is not enough to take the arm RX11 out of the path of the cam RX23. Therefore, cam RX23 remains locked until the stem of key K11 has fully risen. As soon as the key K11 has fully risen, its stem releases the bell-crank RX6 and the bell-crank then moves to the position shown

in full lines in Fig. 68 thus completely removing the arm RX11 from the path of the cam RX23 and allows the cam to rotate counter-clockwise as seen in Fig. 66. Referring particularly to Figs. 5, 15, 66, and 67, it is seen that the bail-shaped cam RX23 is formed, at its right-hand side into a downwardly extending arm RX65. The arm RX65 contacts a leftwardly bent lug C47 on the cam-rotating slide C38. Thus, as the cam RX23 swings, the arm RX65 moves the slide and rotates the cams C24, independently of any actuating-plate. Shortly after the cams C24 start rotating, the surface C181 (Fig. 57) of the bar C34 moves out of the path of the beveled point C179 of the plate C170 and permits the bar C34 to be moved to the normal locking position under the tension of the springy portions C28.

The movement of cam RX23 is also utilized to complete the raising of the tail of the actuating-plate (AP10 in the present instance). Referring to Fig. 66, the surface RX60, of cam RX23, is an eccentric surface and is so formed that a portion RX66, which is nearest the front of the machine, is nearer the shaft F75 than that portion of surface RX60, which is nearest the rear of the machine. Therefore, when the cam RX23 swings, from its normal position, a surface RX67 rides under the lamination RX50, of slide RX51, and cams the lamination up against the portion RX66, of cam RX23. This raises the tail of the actuating-plate AP10, which was partially raised by action of the cam RX14, to its full extent and thus trips the single-revolution motor-clutch. Simultaneously with the raising of the actuating-plate tail, a rear surface RX68, of cam RX23, strikes the flap RX27 and moves it from its Fig. 82 position halfway back to normal. This causes the slide C150 to be drawn halfway back to normal or to a neutral position so that its toe C181 is withdrawn from under the escapement rack C70. As soon as this happens, the rack C70 returns to its E2 or normal position wherein it engages the stepping dog on the carriage. The carriage then moves one step to the left relative to the stepping dog and thus aligns the cams C24 and the sectors S. At this point it is to be noted that the plate C170 (Fig. 57) does not return to its normal position until near the end of the re-multiplication cycle even though the tab stop C169 is withdrawn from engagement with the lug C177. The reason for this is that the cams C24 and locking bar C34 are rotated before the tab stop C169 is withdrawn from lug C177. Thus, when lug C177 is released, a surface C200, on plate C170, is urged against a surface C201, on the (rotated) locking bar C34. Surface C201 thus prevents the return of plate C170 until the cams C24 return nearly to zero position. From the foregoing, it is seen that if the plate C170 is swung to its operated position and the cams are rotated while plate C170 is in that position, then the cam surface C178 is disabled and the cams C24 remain in a normal locking position.

From the foregoing it is also seen that, as the 65 re-multiplication cycle begins, the cam RX14 is in its operated or Fig. 82 position and is latched down by the latch RX39. Also the cam RX23 is in its operated position wherein its cross-portion RX22 is again abutting the lug RX20, on cam RX14. The ensuing cycle withdraws a total from the upper accumulator and the heels S2 (Fig. 22), of the sectors S, depress the cams C24 correspondingly. At the end of the forward stroke, a lug M50 (see Figs. 66 and 67), integral with 70 the pitman bracket M15, contacts the lower end

of the latch RX39 and swings the latch counter-clockwise (as seen in Fig. 66), thereby releasing cam RX14. The spring RX24 then returns both cams RX14 and RX23 to normal. When the cam RX23 thus returns to normal, the arm RX65, integral therewith, moves away from the lug C47 on the slide C38. However, the slide C38 cannot return to its forward normal position under tension of its spring C42, due to the fact that at this time the shoulder AP55 of the actuating plate AP10 is in engagement with the lug C38 of the slide C38. On the return movement of the actuating plate AP10 the lug C39 follows the shoulder AP55 and consequently the cams C24 of the cam carriage are returned from their 90° position to normal position. After cam RX23 returns to normal, the slide C150 is still held in its neutral position due to the fact that the escapement rack C170 now blocks the toe C151, of slide C150, against forward movement. At the end of the return stroke, the nose AP60 (Figs. 74 and 75), of the actuating-plate AP10, operates the rock-lever C154 and the lever C154, in turning, raises the front end of the rock-lever RX23 which moves the lug RX32 from the shoulder RX31 and thus releases the lever RX26. Lever RX26 immediately returns to its normal position and causes the flap RX27 to pull slide C150 to normal or rearward position. Thus all parts are restored to their normal positions. It is to be noted that no carriage return is effected during re-multiplication cycles because the rock-lever RX26 holds the slide C150 in such positions that its front end is always raised and consequently the slide C150 is not allowed to operate the latch-plate C134 (Fig. 82).

If it is desired to use the re-multiplication mechanism in connection with the lower or grand-total accumulator, then the key K12 is depressed and held while the key K11 is depressed. Depression of key K12 (see Figs. 66 and 67) causes an end RX10 thereof, to be depressed. This causes a cam surface RX71 to engage the slide RX51 and cam the slide bodily toward the right-hand side of the machine which removes the finger RX56 from alignment with the actuating-plate AP10 and into alignment with the plate AP11. Thus the grand-total actuating-plate moves instead of the plate AP10 and a total taking is extracted from the lower accumulator and impressed upon the cams C24.

It is to be noted, in connection with the re-multiplication mechanism, that a true negative total can be printed without the use of any "fugitive one" mechanism. Assume that the upper accumulator contains a negative total. This would read, on the accumulator dials, as a complementary amount. The operator depresses the key K11 thus impressing the complementary amount upon the cams C24. The operator then hits the subtraction palm-bar and this subtracts the complementary amount from the cleared upper accumulator. The dials will then show the true negative balance.

It is also to be noted that a total can be transferred from the lower to the upper accumulator as follows: The operator depresses and holds the key K12 and then depresses key K11. This withdraws the total from the lower accumulator and impresses it upon the cams C24 of the cam-carriage. The operator then hits the addition palm-bar and this runs the extracted total from the cams C24 into the upper accumulator.

CONSTANT-FACTOR MECHANISM

Referring to Figs. 72 and 73, the constant factor key K10 is loosely mounted in a slot in the keyboard plate F8. The key K10 is shouldered at K16 and K17 and is so arranged that the portion of the key, which is below the shoulder K17, passes through a slot in a flat spring K14 and is thus supported and urged upward by the spring. The spring K14 is fastened to the keyboard plate F8 by a screw K18 (Fig. 73). The key is operated by pushing it down and moving its top toward the right of the machine. This latches the shoulder K16 under the keyboard plate F8. The key is released by moving its top portion back toward the left side of the machine. This removes shoulder K16 from the plate F8 and the spring K14 moves the key upward to its normal position.

20 A swinging frame CF1 (Figs. 72 and 73) is formed, at its rear end, around the shaft F78 so that the frame pivots freely upon the shaft. The front end of frame CF1 is made with a circular shape and is drilled at its center to receive a large shouldered rivet CF2. The rivet CF2 is hollowed out so as to permit the shank of the pulley C113 to pass therethrough. Loosely mounted upon the rivet CF2, is a gear segment CF3 which segment is made with four radially extending teeth thereon (Fig. 72). One of these teeth CF4 is longer than the rest as shown. An expansion spring CF5 is coiled about the shank of the pulley C113 and is anchored at opposite sides of the swinging frame CF1 and gear segment CF3 so that the spring tends constantly to hold the segment in its normal position, shown in Figs. 72 and 73. Thus, no matter in which direction the gear segment CF3 may be rotated, the spring CF5 always tends to return it to normal. 40 From the foregoing, it is seen that whenever the constant factor key K10 is latched down, the swinging frame CF1, and hence the gear segment CF3, are swung counter-clockwise so that the teeth of segment CF3 mesh with the teeth RX2 of the gear RX1. Pivotaly mounted upon a shouldered rivet CF7, which rivet is fast in the swinging frame CF1, is a rock-lever CF8. The right-hand end CF9, of lever CF8, is offset downwardly so as to clear the teeth of the gear segment CF3. However, when the constant-factor key K10 is latched down, the end CF9, of lever CF8, lies in the same plane as the long tooth RX3 of the gear RX1. Pivotaly mounted upon the shaft F75 is a lever CF11, the forward end of which is formed into a stop CF12. The stop CF12 extends upwardly through a slot CF13 in the swinging frame CF1, the slot CF13 being indicated in dotted lines in Fig. 73. The slot CF13 and stop CF12, therefore, act to keep the lever CF11 from moving laterally upon shaft F75. The rear end of lever CF11 is formed with a cam point CF15, thereon, which cooperates with the flap RX27 to move the slide C150, the flap RX27 being cut away, at its right-hand end, to allow for the lever CF11. An expansion spring CF16 coiled about shaft F75, is anchored, at one end, under the rear of the swinging frame CF1 and is anchored, at its other end, under the lever CF11 as shown in Fig. 72. The spring CF16 tends constantly to hold the stop CF12, of lever CF11, in its uppermost position (Fig. 73) and also acts, through lever CF11, to hold the entire swinging frame CF1 in its normal position wherein the teeth of segment CF3 are disengaged from the teeth RX2, of gear RX1.

The manner in which the above parts of the constant factor mechanism operate is best understood by the use of a specific example. Therefore, the tax-billing example, given at the beginning of this specification will be used. The constant factor to be used is 5.34. The assessed valuation, shown on the first bill, is \$5,700 and the assessed valuation, shown on the second bill is \$83,500. The machine operator sets up the digits "5," "3" and "4" on the keyboard. This causes leftward stepping of the cam carriage and thus causes the long tooth RX3 (Fig. 72) to move three tooth-spaces clockwise. She then latches down the constant-factor key K10 (Fig. 73), so that the lower end of key K10 contacts the front end of the swinging frame CF1 and rocks the frame counter-clockwise, thus meshing the teeth of the segment CF3 with the teeth of the gear RX1. At this time, the gear RX1 is three tooth-spaces clockwise from its Fig. 72 position, the cam carriage is three steps leftward of its home position and the gear-segment CF3 is in the position shown in Fig. 72. Thus, the new home position of the carriage is three steps leftward from its regular home position and, as long as the key K10 remains latched down, the carriage will not be cleared and will, after every total cycle, be returned to its new home position. Also, depression of key K10 rocks the lever CF11 (Fig. 73) counter-clockwise so that the cam-point CF15 swings the flap RX27 clockwise and thus moves the slide C150 forward to its neutral position. The operator, after latching down the constant-factor key, thumbs the multiplication key K7 and depresses the "7" digit key. The machine then cycles seven times and the cam carriage steps once to the left. This draws the gear RX1 and segment CF3 one step clockwise as seen from the top of the machine. The operator, still holding the multiplication key K7 operated, depresses the "5" digit key and after five cycles the machine stops and the cam carriage steps once to the left. This again moves the gear RX1 and segment CF3 a tooth-space clockwise. The upper accumulator, at this time, contains the product desired. The operator releases the multiplication key and, as was previously explained, the nose AP60, on the multiply plate AP1, swings the rock-lever C154 (Fig. 77) which, in turn, lifts the forward end of slide C150. However, due to the fact that the slide C150 is in its neutral position, the toe C152 (Fig. 76) is just forward of the lug C160 and the toe C151 is not forward quite far enough to engage the escapement rack C70. Therefore, the forward end of slide C150 is idly raised and lowered. The operator, at this time, depresses the total taking palm-bar and a total cycle ensues. At the beginning of the total taking cycle, the cam carriage is pulled to its totaling position, wherein the stepping dog rests upon the right-hand end of the escapement rack, and this (see Fig. 72) turns the gear RX1 and segment CF3 counter-clockwise until the long tooth CF4 passes under and beyond the stop CF12 and the long tooth RX3 hits against a cam surface CF20, on lever CF8. This cams lever CF8 counter-clockwise so that its neck CF21, acting upon an inclined surface CF22 of lever CF11, cams down the front end of the lever CF11. This positions the bottom of stop CF12 in the path of the long tooth CF4 and also causes the cam-point CF15, of lever CF12, to swing the flap RX27 slightly further clockwise (as seen from the right-hand side of the machine) so that slide C150 is moved from

its neutral position to its forward position wherein the toe C151 is positioned under the right-hand end of the escapement rack C70. At the end of the total taking cycle, the actuating plate 5 swings rock-lever C154 (Fig. 74) which lifts the front end of slide C150, and latches it over a projection CF25 (see also Fig. 76) of a flat spring CF26 which spring is screwed to the framing-ear F58. It is to be understood, at this point 10 that if the slide C150 is in its rearward or in its neutral position, the spring CF26 will not latch it but when the slide C150 is in its forward position it cams the spring CF26 toward the left-hand side of the machine and then when the 15 front of slide C150 is raised, the projection CF25 snaps in under it as shown in Fig. 74. This causes the toe C151 (Fig. 76) to swing the escapement rack C70 to its E4 or highest position. As soon as the escapement rack reaches its E4 20 position, the carriage begins to tabulate toward the left-hand side of the machine which causes the gear RX1 (Fig. 72) and segment CF3 to turn clockwise until the long tooth CF4 strikes against the lower portion of the stop CF12. Just before the long tooth CF4 strikes stop CF12, it strikes a cam-edge CF24 (Fig. 72) on lever CF8, and cams the lever CF8 out of its frictional engagement with the lever CF11 so that the stop CF12, of lever CF11, is no longer held down. The action of the long tooth CF4, in striking the surface CF24 to cam lever CF8 clockwise to its normal position, is so fast that the long tooth CF4 strikes against the stop CF12 before the spring CF18 can raise the stop to its normal position, out of the path of tooth CF4. However, the spring CF18 takes effect the moment the tooth CF4 strikes the bottom of the stop CF12 and thus the lever CF11 is returned. As the bottom of 30 stop CF12 rises, the cam point CF15 releases flap RX27 which moves the slide C150 rearward to its neutral position. In the initial part of the movement of slide C150 to its neutral position and before the bottom of stop CF12 has completely risen out of the path of tooth CF4, the slide C150 drops off the projection CF25 (Fig. 74) of spring CF26 and releases the escapement rack C70. The rack swings to its normal E2 position 35 wherein it engages the stepping dog of the carriage. The carriage then moves one step leftward relative to the dog and this brings the tooth CF4 back to the Fig. 72 position. Thus the carriage is returned exactly to its new home position. When using the constant-factor key, the 40 carriage is never cleared. As was explained above, the carriage tabulates to the left, with the escapement rack in E4 position, after every total taking cycle during constant-factor work. The carriage, however, is never allowed to tabulate to the position where it would contact the 45 tabulator stop C169 (Fig. 52) because in this position of the carriage, the leftmost cam C24 is aligned with the leftmost sector S1. With the constant-factor key depressed, the carriage tabulates only to its "new home position" and this 50 position is determined by the number of digits in the constant-factor. Thus a constant-factor of nine digits would have to be introduced to allow the carriage this amount of tabulation and 55 such large constant-factors are never necessary. The constant-factor key K10 may be used as a regular repeat key as follows: A number is set up in the cam carriage and the key K10 is latched down. The addition or the subtraction palm-bar 60 may then be depressed any number of times and

the carriage will remain in one position and will not be cleared.

It is also to be noted that a number may be added into one accumulator and subtracted from the other, in two machine cycles, with but one set up of the number on the digit keys. This is accomplished as follows: Assume that it is desired to add the number 125.37 into the upper accumulator and to subtract it from the lower accumulator. The operator sets up the digits 12537 on the keyboard and then latches down the constant-factor key. She then hits the add palm bar, inserting the amount 12537 in the upper accumulator. The operator then thumbs over the accumulator-shift key K1 and holds it while she depresses the subtraction palm bar K2. This subtracts 12537 from the lower accumulator. The operator then releases the constant-factor key and operates the correction key K4 which clears the carriage and returns it to its original home position.

While I have described what I consider to be a highly desirable embodiment of my invention, it is obvious that many changes in form could be made without departing from the spirit of my invention, and I, therefore, do not limit myself to the exact form herein shown and described, nor to anything less than the whole of my invention as hereinbefore set forth, and as hereinafter claimed.

What I claim as new, and desire to secure by Letters Patent, is:

1. In a machine of the class described the combination of an accumulator, a plurality of actuating racks, a plurality of actuating elements, each formed with a definite and distinctive pattern for actuating various mechanisms of said machine to cause a definite and distinctive cycle of operation of said machine in accordance with said pattern, means for selectively driving said actuating elements, means operable by said actuating elements for driving said actuating racks, and means operable by said actuating elements for engaging and disengaging said accumulator and said actuating racks.

2. In a machine of the class described the combination of an accumulator, a plurality of actuating racks, a plurality of actuating elements, each formed with a definite and distinctive pattern for actuating various mechanisms of said machine to cause a definite and distinctive cycle of operation of said machine in accordance with said pattern, means for selectively driving said actuating elements, means operable by said actuating elements for driving said actuating racks, means including a ball movable in a plurality of positions to engage and disengage said accumulator and said actuating racks, and means on said actuating elements for moving said ball in said plurality of positions.

3. In a machine of the class described the combination of main operating mechanism for said machine, an accumulator, a plurality of accumulator-actuating elements, means operable by said main operating mechanism for differentially positioning said accumulator-actuating elements, means for displacing said positioning means from cooperation with said accumulator-actuating elements, and separate means for differentially positioning said accumulator-actuating elements when said positioning means is displaced.

4. In a machine of the class described the combination of main operating mechanism for said machine, an accumulator, a plurality of accumulator-actuating elements; a plurality of ro-

tatable members selectively settable to various positions of eccentricity operable by said main operating mechanism for differentially positioning said accumulator-actuating elements; means for displacing said last mentioned means from cooperation with said accumulator-actuating elements, and separate means for differentially positioning said accumulator-actuating elements when said rotatable members are displaced.

5. In a machine of the class described wherein amounts are entered from a set of digit keys into an amount-receiving device which is movable step-by-step from a home position for controlling a plurality of accumulator actuating elements and wherein said amount-receiving device is normally cleared and returned to home position at the end of each operating cycle of said machine, the combination of main operating mechanism, a key, means operable by said key for disabling the clearing and returning of said amount-receiving device, an accumulator, means for controlling said accumulator-actuating elements to extract a total from said accumulator, means operable on a total cycle for taking said amount-receiving device out of engagement with said accumulator-actuating elements, and means for causing said amount-receiving device to resume, after a total cycle of said machine, the position it assumed before operation of said key.

6. In a machine of the class described the combination with main operating mechanism of an accumulator, a plurality of accumulator actuating elements, a plurality of digit keys, an amount-receiving device movable step-by-step from a home position for controlling said accumulator actuating elements, means operable by said digit keys for entering amounts into said amount receiving device, means for controlling said accumulator actuating elements to extract a total from said accumulator, means normally operable to clear said amount-receiving device on certain total cycles of said machine, and means for disabling said clearing means on certain other total cycles of said machine.

7. In a machine of the class described the combination with main operating mechanism of an accumulator, a plurality of accumulator actuating elements, a plurality of digit keys, an amount-receiving device movable step-by-step from a home position for controlling said accumulator actuating elements, means operable by said digit keys for entering amounts into said amount receiving device, means for controlling said accumulator actuating elements to extract a total from said accumulator, means for moving said amount-receiving device out of engagement with said accumulator actuating elements on each total cycle, means for moving said amount-receiving device to home position on certain total-cycles of said machine and means for moving said amount-receiving device to a predetermined position on certain other total-cycles of said machine.

8. In a machine of the class described, the combination of a plurality of normally inactive actuating elements each formed with a definite and distinctive pattern for actuating various mechanisms of the machine to cause a definite and distinctive cycle of operation of said machine in accordance with said pattern, and means for moving any one of said actuating elements into active position, said means including a plurality of elements each positioned in cooperative relation with one certain actuating ele-

ment and shiftable into cooperative relation with another one of said actuating elements.

9. In a machine of the class described, the combination of a plurality of actuating elements each formed with a definite and distinctive pattern for actuating various mechanisms of the machine to cause a definite and distinctive cycle of operation of said machine in accordance with said pattern, a power source, a driving device, and means for causing engagement of any one of said actuating elements with said driving device and concomitantly coupling said power source to said driving device, said means including a plurality of elements, each normally in cooperative relation with one certain actuating element and shiftable into cooperative relation with another one of said actuating elements.

10. In an accounting machine, the combination of a differentially movable element, a variably settable eccentric for moving said element differentially in accordance with the setting of said eccentric, a plurality of keys, and means operable by said keys to set said eccentric to any one of a plurality of positions, said means including a member common to said digit keys and movable thereby to any one of a plurality of positions, a setting element engageable with said member to set said eccentric when said member is moved, and an additional element operable upon the depression of said digit keys for engaging said member with said setting element.

11. In a machine of the class described, having an amount receiving device including a plurality of settable elements for controlling the movement of a plurality of accumulator actuating elements and means normally operable at each operating cycle of the machine whereby said amount receiving device is cleared and returned to a home position wherein some of said settable elements are in cooperative relation with some of said actuating elements, the combination of a key capable upon depression thereof to cause a total operation of the machine, means operable by said key for moving said amount receiving device to a position wherein all of said settable elements are out of cooperative relation with said actuating elements, and means whereby said normally operable means is rendered effective at the end of a total operation of the machine to clear and return said amount receiving device to home position.

12. In a machine of the class described, the combination of a main operating mechanism for said machine, a movable carriage, a plurality of rotatable members in said carriage, means for positioning said members to differential amounts of eccentricity to their common center, an accumulator, a plurality of accumulator actuating elements, and means operable by said main operating mechanism for oscillating said members to position said elements in accordance with the eccentricities of the respective members.

13. In an accounting machine, the combination of a differentially movable element, a rotat-

able member settable to varying amounts of eccentricity for moving said element predetermined differential amounts in accordance with the eccentricity, a key, and means operable by said key to individually set said rotatable member to a predetermined amount of eccentricity.

14. In a machine of the class described, a movable carriage, a plurality of rotatable members in said carriage, a normally ineffective element for setting said rotatable members to predetermined amounts of eccentricity in accordance with the amount entered in the machine, an escapement mechanism for causing step-by-step movement of said carriage, a plurality of digit keys, a slidable member, means operable by said slidable member when moved in one direction to render said setting element effective to set said rotatable members, additional means operable by said member when moved in the opposite direction to cause operation of said escapement mechanism, and means on said digit keys to move said slidable member in one direction upon depression and in the opposite direction upon restoration thereof.

15. In a machine of the class described, a movable carriage, a plurality of rotatable members in said carriage for mechanically representing amounts entered in said machine, means for selectively setting said members in predetermined positions differing in eccentricity, means for retaining said members in their selected positions, an escapement rack movable to a position to effect step-by-step movement of said carriage, and means operable by said escapement rack when moved beyond said position to disable said retaining means.

16. In a machine of the class described, a movable carriage, a plurality of rotatable members in said carriage for mechanically representing amounts entered in said machine, means for selectively setting said members in predetermined positions differing in eccentricity, means for retaining said members in their selected positions, an escapement rack movable to a position to effect step-by-step movement of said carriage, a universal member common to said retaining means, and an element operable by said escapement rack when moved beyond said position to move said universal member to disable said retaining means.

17. In a machine of the class described, an accumulator, rack sectors for entering amounts in said accumulator, said sectors having a U-shaped portion thereon, a plurality of discs located in said U-shaped portions, each of said discs being normally concentric to a common shaft, digit keys adapted to set said discs to a predetermined eccentricity relative to said shaft in accordance with the value of the digit, and operating means for rocking said shaft to effect the swinging of said sectors to enter amounts in said accumulator.
